MACHINE AND METHOD FOR APPLYING
PRESSURE TO SHOE BOTTOMSSidney J. Finn, Beverly, Mass., assignor to
United Shoe Machinery Corporation, Paterson, N. J., a corporation of New Jersey

Application November 4, 1936, Serial No. 109,123

150 Claims. (Cl. 12—36)

This invention relates to machines for operating on shoes and is illustrated herein as embodied in a machine for applying pressure to shoe bottoms.

Objects of the invention are to provide an improved machine for laying or cement attaching soles to shoe bottoms which will be adapted to operate on shoes of all shapes or sizes, to provide improved mechanism for positioning a sole and shoe relatively to each other before the sole is attached to the shoe, to provide improved means for relatively locating and supporting the heel portion of a sole and shoe before pressure is applied thereto, and to provide simplified and improved means for covering portions of an inflatable pressure-applying pad which are located outside the periphery of a shoe mounted thereon to prevent the pad from bending the edges of the sole excessively during the application of pressure to the shoe bottom. Further objects of the invention, as pointed out more particularly hereinafter, include the provision of improved arrangements for insuring that substantially the same pressure is applied to all shoes irrespective of their shapes or sizes, the provision of improved means for locking the shoes in pressure receiving position in the machine and for automatically effecting their release after pressure has been applied, and the provision of improved pressure-applying means and mechanism for actuating and controlling said means. A still further object is to provide an improved method of cement attaching soles to shoes.

To the attainment of these objects and in accordance with one feature of the invention, the machine, as herein illustrated, is provided with an improved shoe receiving pad normally located in a substantially flat position. Means in the form of a holdown is provided for pressing the forepart of a shoe firmly against the pad, thereby clamping the shoe on the pad and holding the shank and heel portions of the shoe away from the rear portion of the pad, and further means is provided for effecting relative movement between the shoe and pad to bring the rear portion of the pad into operative engagement with the shank and heel portions of the shoe bottom, thereby conforming the pad to the shoe bottom irrespective of the size or shape of the shoe. As illustrated herein, the means for pressing the forepart of the shoe against the pad and the means for effecting relative movement of the pad and shoe to bring them into engagement with each other are treadle operated and are arranged to be locked in operative

positions prior to and during the pressure-applying operation.

In accordance with another feature of the invention, gages are provided on the pad for relatively positioning a sole and shoe thereon, these gages being constructed and arranged to find the edge face of the sole placed loosely on the pad without moving the sole and thus to determine the position of the shoe relatively to the sole. The positioning gages, as illustrated herein, are arranged to move toward and from a sole on the pad in straight paths preferably located substantially at right angles to the edge face of the sole, and means is provided for locking the gages in their paths upon their engagement with the sole, the last-named means being operated automatically by contact of the gages with the sole. Means is also provided for simultaneously operating the gages until each gage contacts with the edge of the sole and the illustrated arrangement is adapted to permit the gage operating means to complete its operative movement after one or more of the gages have contacted the sole without interfering with the positions of the contacting gages.

In accordance with still another feature of the invention improved means is provided for engaging the heel portion of a sole and holding it against movement laterally of the pad. Further means, acting in conjunction with the sole engaging means, is provided for finding the heel portion of the shoe clamped against the sole and for shifting the sole engaging means laterally of the shoe to move the rear portion of the sole into proper alignment with that portion of the shoe bottom. Since the shank and heel portions of the shoe, as stated above, are spaced from the pad and the sole thereon by reason of the pressure applied to the forepart of the shoe, the rear portion of the sole will thus be moved into proper position relatively to the shank and heel portions of the shoe bottom while the rear portion of the sole is free from the weight of the shoe or from pressure applied to the shoe by an operator while the shoe is engaging the full length of the sole.

The shoe finding means, as herein illustrated, carries mechanism for engaging the last in the shoe and thereby supporting the heel portion of the shoe against pressure from the pad. Further means is provided on the pad-supporting mechanism for maintaining the last engaging and shoe finding means when not operating in a predetermined position relatively to the pad and for returning them to such position after they have operated but permitting them to move out of this

position when they are moved toward the sole and shoe on the pad, thereby permitting them to find the shoe and last irrespective of the position of the shoe widthwise of the pad and simultaneously 5 to shift the sole laterally into proper alignment with the shoe bottom by cooperation with the sole gaging means. Means for locking the last engaging and supporting means and the shoe finding means in operative position is also provided so 10 that after the pad has been conformed to the shoe bottom and pressure is to be applied to the shoe by inflation of the pad, the last and shoe will be rigidly supported to withstand the pressure.

The invention also provides, in accordance with 15 still another feature, improved means for covering a portion of the pad located outside the periphery of the shoe bottom to prevent excessive bulging of such portion when the pad is inflated and thereby to prevent bending the edge of the sole too greatly 20 during the pressing operation. As herein illustrated, the covering means comprises a mask plate arranged to overlie the forward portion of the pad and mounted for movement in a fixed path longitudinally of the pad to cause the mask 25 plate to approach the edge of a shoe mounted thereon. Means for moving the mask plate toward and from the shoe comprises automatically operated connections between said mask plate and the holdown means for pressing the fore- 30 part of the shoe against the pad. Accordingly, when the forepart holdown means is actuated, the mask plate is moved automatically toward or away from its operative position relatively to the shoe. The connecting means illustrated here- 35 in comprises a toggle which, when straightened, is arranged to move the mask plate toward its operative position. In order to locate the mask plate in a predetermined position relatively to each shoe operated upon irrespective of the size of the shoe, the toggle carries further mechanism 40 including a finger arranged to engage the toe end of the sole as the mechanism is operated and to break the toggle, thereby causing the mask plate to cease its movement while the pressing means continues to move into engagement with the shoe. 45 In returning the mask plate to inoperative position the toggle is first straightened automatically by reverse movement of the pressing means and then acts to retract the mask plate while simultaneously positioning itself for its next operative 50 action. Further means carried by the toggle is also provided for automatically moving the finger away from the toe end of the sole after the toggle is broken so that there will be no chance of the finger catching on the edge of the sole while the shoe is being removed from the machine and thereby pulling the sole away from the shoe bottom or weakening its attachment thereto.

In applying pressure to the shoe bottom the 55 illustrated machine is arranged, in accordance with another feature of the invention, to produce substantially the same amount of roll or convexity on the outsoles of all shoes irrespective of their sizes or shapes. This is accomplished, as 60 herein illustrated, by making the chamber in the inflatable pad relatively shallow so that when deflated its opposite walls will contact with each other to form a relatively unyielding shoe receiving layer or wall. The sole and shoe are pressed 65 against this unyielding wall and the mask plate is moved into a predetermined position relatively to the shoe to leave the same amount of pad surface exposed between the mask plate and the shoe bottom for each shoe operated upon irrespective 70 of its size. The pad is then inflated to apply a

predetermined pressure to the shoe bottom, the amount of this pressure being controlled automatically by pressure regulating means associated with the inflating means, so that the pressure is the same for each shoe operated upon and the 5 bulge at the exposed portions of the pad is likewise substantially the same. Since each shoe is located in substantially the same plane relatively to the mask plate, and since the mask plate is positioned the same distance from each shoe, the 10 inflation of the pad the same amount for each shoe will curve or roll the marginal portions of the outsole the same amount toward the shoe upper thereby producing substantially the same 15 convexity on the shoe bottom irrespective of the size of the shoe. Preferably, and as illustrated herein, the inflatable pad is covered by a solid pad of flexible material having means at its forepart for reducing its compressibility a substantial amount to protect the inflatable pad and also to 20 prevent too great a roll or curvature being imparted to the forepart of the shoe bottom.

In order to operate successively on right and left shoes, the illustrated machine is provided with two operating stations located side by side and 25 each having a complete set of operating mechanism associated therewith, both sets of operating mechanism being of substantially the same construction except that the parts are reversed with respect to each other. After one station is loaded 30 with a right or left shoe as the case may be and pressure is being applied to the sole and shoe, the other station is loaded with the proper shoe preparatory to applying pressure thereto. Since the shoe in the first station will be ready to be released 35 when pressure is to be applied to the shoe in the second station, thereby to permit another sole and shoe to be mounted in said first station without loss of time by the operator, the machine is provided, in accordance with still another feature of 40 the invention, with means for automatically releasing the sole and shoe in either station through the operation of mechanism on the opposite station when the latter station is ready to apply pressure to the sole and shoe mounted therein. 45 As herein illustrated, the automatic releasing means is operated when the operator actuates the pad inflating means in the station which is to apply pressure and is opposite that which is to be released and this releasing means acts first to 50 cause the pressure to be relieved in the pad on the station being released and thereafter to unlock the pressing means which is holding the forepart of the shoe against the pad. After the pressing means is unlocked, tension on further mechanism 55 associated with this same releasing station is relieved to cause means associated with such mechanism to release the last engaging and heel supporting member which, as stated above, carries the shoe finding means. This mechanism is then 60 permitted to return of its own weight to its inoperative position. Thereafter, the pad conforming and supporting mechanism for this releasing station is automatically unlocked to permit the rear portion of the pad to return to its initial flat position, thereby leaving the shoe free to be removed 65 from the pad.

As indicated above, the forepart holdown for 70 pressing the shoe against the pad is locked in operative position and the locking means therefore is operated automatically by movement of the holdown or pressing means toward the shoe. Other features of the invention comprise the provision of improved means for unlocking the sole and shoe gages and returning them posi- 75

5 tively to inoperative position before the pad associated therewith is inflated, the provision of improved treadle constructions whereby one treadle may be utilized first to operate the pressing means or forepart holdown and thereafter to operate the pad conforming means and the inflating mechanism in proper timed relation to each other.

10 Improved fluid pressure controlling means is also provided on the machine, this means being constructed and arranged, in accordance with still another feature of the invention, to admit fluid under pressure to the pad on one station while permitting the pad at the other station to 15 exhaust. As herein illustrated, means operated by the holdown and pad conforming treadle is constructed and arranged, during operation of that treadle in moving the rear portion of the pad into operative relation to the shoe bottom, 20 to "set" or position this pressure controlling means so that the pad which is next to apply pressure to a sole and shoe will be inflated by the operation of the inflating mechanism and also so that the pad which is then applying pressure 25 to a sole and shoe will exhaust, this exhausting action taking place immediately upon the positioning of the controlling mechanism and thereby preparing the exhausting station for the release of the shoe therein. The inflating action 30 of the other pad, however, is postponed until, through further depression of the same treadle, pad inflating means located at the rear of the machine is actuated, this treadle movement simultaneously operating the automatic release 35 mechanism in the opposite station as explained above.

40 In accordance with a further important feature of the invention, pad inflating means at the rear of the machine is actuated and automatically controlled by mechanism including a valve normally arranged to prevent fluid under pressure from passing into either of the pads but adapted to be actuated at the proper time to cause fluid to pass into one of the pads. As 45 herein illustrated, the valve is moved to open or close a conduit or pipe line leading from a common source of supply to each of the pads. When the pipe line is open the fluid is returned to a reservoir from which it was taken and, when 50 the pipe line is closed by the valve, the fluid passes under pressure into that pad which is next to apply pressure to the shoe bottom, this pad being determined by the position of the fluid pressure controlling mechanism which has been 55 previously set, as explained above. The pad inflating means, as illustrated herein, is actuated by the last part of the operation of the holdown treadle but the operation of said means is terminated automatically after the pressure in the pad 60 reaches a predetermined amount. As illustrated, the operation of the inflating mechanism is stopped indirectly by the action of the pressure regulator referred to and which automatically controls the pressure in the pad. When the required pressure is attained, the regulator permits additional fluid pumped from the reservoir to pass through an opening in the regulator into a container carried by a pivoted lever which is so positioned and arranged that, when the 70 weight of the fluid in the container overcomes the weight of the lever the latter swings about its pivot to operate further mechanism which actuates the valve and thus opens the pipe line to empty further fluid into the supply reservoir. 75 In this way each pad is inflated to a predeter-

mined pressure and the operation of the inflating mechanism is stopped automatically so that the mechanism must be actuated again manually before the pad in the other station can be inflated.

5

10 In its method aspect the invention provides an improved process of cement attaching soles to shoes which comprises locating a sole relatively to a shoe bottom, applying pressure to the foreparts of the sole and shoe while holding the shank and heel portions of the sole away from the shoe bottom, and then moving the shank and heel portions of the sole into engagement with corresponding portions of the shoe bottom thereby laying the sole and applying pressure to it 15 and the shoe progressively throughout the shank and heel portions.

20 The above and other objects and features of the invention, including also various other novel combinations and arrangements of parts, will now be described in connection with the accompanying drawings and thereafter pointed out in the claims.

25 In the drawings,

Fig. 32 is a side elevation on an enlarged scale of a portion of the valve mechanism shown in Fig. 31; and

Fig. 33 is a fragmentary sectional view of a member which automatically stops the operation of the valve mechanism.

The machine comprises a base 10 and an upwardly slanting frame 12 the upper end of which slants downwardly toward the front of the machine at an angle of about 45° to the horizontal and carries at its opposite sides pad-supporting members or boxes 14, 16 each provided with a relatively solid pad 18 and 20 the heel portions of which are toward the operator, as shown in Fig. 1, the pads being adapted to operate respectively on right and left shoes regardless of their sizes or shapes. Since the pads are located at an angle of 45° to the horizontal their entire shoe-engaging surfaces may be readily seen by the operator as he stands at the front of the machine in position to mount a shoe on either pad. The pad-supporting members 14, 16 and the mechanism associated therewith comprise right- and left-hand pressure-applying stations which are substantially identical in construction except that the mechanisms are reversed relatively to each other. Accordingly, only the mechanism on the right-hand station of the machine has been illustrated in detail and the description will be confined to that station, it being understood that the opposite station is of substantially the same construction.

The pad 18 and pad supporting mechanism 14

of the right-hand station are best illustrated in Figs. 4, 5 and 7. The pad-supporting mechanism or pad box comprises a casting 22 bolted to the upper end of the frame 12 and having an upstanding wall 24 on its inner end and side portions which provides a recess for receiving the forepart of the pad 18. On its lower side the casting 22 has a cylindrical projection 26 (Figs. 5 and 12) into which is threaded a flexible hose 28 which communicates with a chamber 30 (Fig. 10) 12) provided with an opening 32 in which is mounted a bushing 34 having a flange 35 (Fig. 5) at its upper end between which and the casting the lower wall of an inflatable pad 40 is clamped, the bushing 34 having holes 36 at its lower portion for admitting fluid under pressure to the pad and being clamped in position by a screw 38 threaded into its lower end.

The pressure-applying pad comprises the solid upper pad 18 and the lower inflatable pad 40 preferably of rubber and conforming substantially in outline to the periphery of the shoe bottom but being large enough for the largest shoe which is to be operated upon. The inflatable pad 40 has a shallow chamber 42 which is normally collapsed by the weight of the upper pad, as shown in Fig. 5, but which may be expanded by fluid pressure to a considerable height in applying pressure to a shoe bottom. The solid pad 18 has a portion of relatively thick rubber for engaging the shank and heel portions of the shoe bottom and molded to conform approximately to the shape of such portions. This thick portion of the pad is provided at its periphery with a downwardly extending flange 44 which forms a recess or pocket in which the outer or heel portion of the inflatable pad 40 may be conveniently located. The lower surface of the heel portion of the solid pad 18 is provided with a stiffening member or plate 46 (Fig. 13) preferably of metal for maintaining this portion of the pad 18 in a substantially flat position even under substantial pressure.

The forepart portion of the upper or sole-engaging pad 18 is considerably thicker than its heel portion and is preferably provided with a plurality of substantially rectangular compartments or cells 48 filled with relatively fluent material such as sand which becomes rigid or "set" under pressure, thereby rendering the forepart of the pad 18 relatively inflexible so that the marginal portions of its upper surface will not bulge excessively when pressure is applied and thus cause the marginal portions of the forepart of the sole to become too greatly rounded. The construction of the forepart of the pad 18 may be substantially the same as the pad disclosed in Patent No. 2,064,900 granted December 22, 1936 on my application and reference may be had to that patent for a more detailed description thereof. It will be noted, however, that initially the upper or shoe engaging surface of the pad 18 lies in a substantially flat plane, this plane being located at about 45° to the horizontal. Consequently, except for the molded portion at the shank, the exposed surface of the pad is relatively flat from one end to the other.

At their forward portions the opposite side walls 24 of the pad supporting member 22 are recessed, as shown at 50 in Fig. 10, to receive opposite side portions of a central pad supporting member 52 which is pivoted to the walls by pins 54 (only one of which is shown in Figs. 5 and 10) and which underlies the central portions of the pads 18 and 40 and is strengthened by a trans-

verse rib 56. The intermediate member 52 is pivotally connected by pivot pins 58 to a forward or heel supporting section 60 provided with an upstanding wall 62 within which the heel portions of the pads are located. The space between the pad-supporting members 22 and 52 is covered by a thin plate 64 pivoted on a pin 66 secured in the supporting member 22, the portion of the plate which extends forwardly toward the operator resting in a recess 68 formed in the intermediate member 52. The space between the members 52 and 60 is covered by a relatively thick piece of flexible material 70, such as leather, the marginal portion 72 of which is tapered to prevent cutting the lower pad.

The pad supporting sections 52, 60 of the pad box extend outward and downwardly at about 45° from the stationary member 22 and means is provided for supporting these members in their inclined position and for moving them relatively to the member 22 to conform the pads 18, 40 to the shank and heel portions of the bottom of a shoe to which pressure is to be applied. The means for supporting the rear sections of the pad box comprises a yoked member 74 (Fig. 5) pivoted to the frame 12 on pins 76 and having opposite side arms which normally extend downwardly and forwardly at about 45° to the horizontal. At its lower end the yoked member 74 has a projection or lip 78 arranged to engage an adjustable block 80 slidably mounted on the upper end of a pad supporting bar 82 which is operated as hereinafter described to move the rear pad supporting sections toward the shoe to lay the pad and the sole thereon against the shank and heel portions of the shoe bottom. The block 80 has a T-slot 84 (Fig. 8) whereby it is slidably mounted on the upper end of the bar 82 and stop pins 86 are provided for limiting the sliding movement of the block. The right-hand portion of the block 80 (as viewed in Fig. 8) projects upwardly and has a surface or guideway 88 thereon for engaging the projection 78 and supporting the arms 74 in a relatively high initial position when operating on shoes having deeply arched shank portions and the block also has a lower surface 90 at its left-hand side for supporting the arms 74 in a lower position when operating on shoes having relatively flat bottoms. The stop pins 86 serve to locate these surfaces under the projection 78. The construction and operation of the pad supporting bar 82 and the mechanism associated therewith will be explained hereinafter in connection with the operation of moving the movable sections of the pad box into operative position relatively to the shank and heel portions of the shoe bottom.

The heel supporting section 60 of the pad box is provided at its inner end with a transverse pin 92 to the opposite ends of which are pivotally secured downwardly extending links 94, the lower ends of these links being pivotally connected to the opposite arms of the yoked member 74 by a transverse pin 96. The links 94 support the inner end of the heel section 60 and also permit longitudinal movement of that section relatively to the arm 74 during the pad-conforming operation.

Inside the links 94 the pin 92 has secured there- 70 to a pair of forwardly inclined arms 98, only one of which is shown in Figs. 5 and 7. At their lower ends the arms 98 are connected together by a transverse pin 100 having mounted on its opposite ends, adjacent to arms 98, light torsion springs 75 102 each of which is hooked under an arm 98

and the other ends of which extend upwardly (Fig. 20) and are hooked into projections 103 formed on the under side of a relatively thin U-shaped plate 104 overlying the heel portion of the pad and mounted for sliding movement longitudinally thereof.

The forward portion of the heel supporting section 60 projects downwardly, as shown in Fig. 5, and is provided with a flat surface 106 of substantial width for engaging different surfaces 10 formed on a rectangular block 108 rotatably mounted between the opposite arms of the yoked member 74 on a pin 110. The block 108 is eccentric on the pin 110 so that each surface is located a different distance from the axis of the 15 pin. The block can be rotated manually on the pin to position its different surfaces for engagement with the flat surface 106, there being sufficient friction between the block and pin to hold the block in any position into which it is moved. 20 The block 108 provides a further means for initially positioning the heel supporting section 60 of the pad box relatively to the arm 74 for accommodating shoes having heels of different heights. 25

The upper surface of the side wall 62 of the heel section 60 has fastened thereto by screws 112 a fixed pad confining plate 114 (Figs. 1 and 5), the rear and side portions of which project forwardly beyond the section 60 and the inner edge 30 of which conforms substantially to the periphery of the heel portion of a shoe and overlaps the margin of the pad 18, thereby retaining the pad in the section 60. The opposite side walls of the shank supporting section 52 likewise have secured 35 thereto by screws a pair of pad confining plates 115 (Fig. 1) which also overlie the marginal portions of the pad and retain it in the member 52. The plate 104 is slidably mounted on the upper surface of the plate 114 by means of downwardly 40 hooked portions 115 (Fig. 20) which overlap the opposite edges of the fixed plate 114 and carry the projections 103 to which the springs 102 are secured. The inner edge of the plate 104 likewise conforms to the heel portion of a shoe, except 45 that it is considerably larger.

The slide plate 104 has formed integrally with its forward portion a transverse tongue 116 (Figs. 5 and 20) upon which is adjustably mounted a carrier member 118 held in position by screws 120 50 located in countersunk slots 122 (Fig. 23) and bearing on washers 124 which overlap shoulders on the countersunk slots, thereby preventing the member 118 from being lifted off the tongue while permitting its adjustment transversely of the pad. 55 At its opposite sides the carrier member 118 is provided with upstanding lugs 126 between which is pivotally mounted on pins 128 a sole-locating tongue or finger 130 riveted to a plate 132 the opposite ends of which project upwardly and encircle the pins. The left-hand portion of the plate 132, as viewed in Fig. 20, has an arm 134 projecting laterally therefrom and between this arm and the plate 104 is secured a spring 136 arranged to move past the center of the pivot 128 as 60 the tongue is swung about said pivot and thereby to hold the tongue either in its operative position against the pad or in an elevated position determined by a stop pin 137 mounted in the boss 65 126 and arranged to engage the arm 134. 70

The sole locating tongue 130 extends inwardly over the heel portion of the pad and is provided at its inner end with a short pin 138 which is perpendicular to the tongue and is arranged to enter a hole in the heel portion of the sole and thereby 75

to position said portion transversely of the pad. The sole is positioned longitudinally of the pad by movement of the slide plate 104 forwardly and rearwardly by the operator when mounting the sole thereon, the light torsion springs 102 referred to above serving to hold the plate and tongue in position on the section 60 and preventing them when not in use from sliding off the forward end of the section 60 which is normally inclined at an angle of 45° to the horizontal.

The tongue 130 is adjusted laterally of the pad by an eccentric adjusting member 140 (Figs. 20 and 22) having a frusto-conical portion 142 rotatably mounted in the carrier member 148 and having a pin 144 projecting from the edge of its lower surface into a transverse slot 146 in the slide plate 104. The member 142 is provided with a handle 148 whereby it can be rotated in the carrier member to move the slide plate 104 transversely of the pad along the tongue 116 and thereby to adjust the tongue 130 laterally of the pad. A compression spring 150 mounted in a hole in the frusto-conical portion of the adjusting member and bearing against a plate 152 provides sufficient friction for holding the member 142 in any adjusted position. In use the operator lifts the tongue 130 away from the pad, lays a sole on the pad and inserts the pin 138 in the hole in the heel portion of the sole. He then lets the tongue drop under the influence of the spring 136 to press the sole lightly against the pad. If the tongue does not originally locate the sole in a relatively central position the operator then adjusts it into such position by the handle 148.

The pad supporting section 22 has secured to its upper surface by screws 153 a thick cover plate 154 (Figs. 1, 4 and 11) and a relatively thin fixed mask plate 156, the inner portion of which engages the marginal portion of the pad 18 and confines it in the member 22. The inner edge faces of the cover plate 154 and the fixed mask plate 156 conform substantially to the contour of the forepart of a shoe bottom and the cover plate 154 is cut away on its lower side, as shown at 158 in Fig. 11, to provide a recess for a movable mask plate 160. The construction and operation of the movable mask plate will be described more fully hereinafter.

The thick cover plate 154 is provided on its upper surface with four upstanding projections 162 (Fig. 1) which are slotted lengthwise to provide T-shaped guideways 161 (Figs. 2 and 3) for individual sets of sole and shoe positioning mechanisms or gages 164 arranged to slide in the guideways toward and away from a sole and shoe mounted on the pad. As illustrated in Fig. 1, the forward sets of gage mechanisms are located substantially opposite the ball line of a shoe mounted on the pad and the rear gages are arranged to move toward the shoe at such angles that they will engage the latter at about the tip line. Except for some differences in dimensions the construction of each set of gages is substantially the same and, accordingly, only one set has been illustrated in detail in Figs. 2 and 3 of the drawings.

As shown in Fig. 2, each set of gages comprises a lower or sole engaging member or feeler 166 which rides freely in the guideway 161 and has secured to its upper side by screws 167 a thick plate 168 which is slotted longitudinally at 170 to receive a shoe-engaging member or gage 172 which is adjustable relatively to the feeler 166. The gage 172 is slotted where the screws 167 pass

through to permit its adjustment relatively to the sole gage 166. The sole gage 166 has a relatively narrow forward edge for finding the edge face of a thin sole on the pad and is arranged to rest lightly on the surface of the pad. The shoe gage 172 has a relatively wide work-engaging surface for engaging the side portion of the shoe upper at the forepart of the shoe. The shoe gage may be adjusted longitudinally of the sole gage or feeler 166 by an eccentric adjusting member 174 similar to the member 140 for adjusting the sole locating tongue 130, a spring being provided, as described above, for creating sufficient friction between the parts to hold the adjusting member in any adjusted position.

At its rear portion the confining plate 168 is cut away on one side (Fig. 2) and carries a transverse pin 176 which has a square head 178 (Fig. 3) that rides in one side of the T-shaped guideway 161. The pin 176 has a bearing near its opposite end in a thin rectangular plate 180 which also rides in the guideway and thus supports the pin in a horizontal position. At its forward end, as viewed in Fig. 2, the pin 176 has pivotally mounted thereon an upwardly extending arm 182 having a laterally projecting cam 184 on its lower portion adjacent to its pivot and in position to engage a hardened steel plate 186 secured to an upper side of the T-shaped guideway 161. When the arm 182 is in the rearwardly inclined position shown in Fig. 2, the cam 184 is free from engagement with the plate 186 and the gage members can slide freely in the guideway toward or from the shoe. When the cam is rotated forwardly or toward the left in Fig. 2 the surface thereon binds against the plate 186 and clamps the gages against further sliding movement in the guideway.

At its upper end the arm 182 is pivotally connected by a link 188 to an upwardly extending arm 190 of a bell-crank lever 192 pivotally mounted on a pin 194 (Fig. 11) extending through ears 196 on a bracket secured by screws to the lower side of the pad supporting section 22. A light tension spring 198 extends between the arm 182 and the arm 190 of the bell-crank lever and tends to maintain the arm 182 inclined rearwardly against a stop pin 199 (Figs. 3 and 11) so that the cam 184 is not engaging the guideway 161 and the gages are normally free to slide therein. Accordingly, when one of the bell-crank levers 192, for example, the right-hand lever as viewed in Fig. 11, is swung in a counterclockwise direction the gage members 166, 172 will slide forwardly as a unit until the sole gage 166 contacts with the edge face of a sole on the pad. Thereupon forward movement of both gage members is arrested and continued movement of the bell-crank lever will rotate the arm 182 away from the stop pin 199 and force the rounded surface of the cam 184 against the plate 186 on the upper side of the guideway 161 and thus lock the gages against further movement. In this way the sole gages of each set are brought inwardly yieldingly to find the opposite edge faces of the sole resting loosely on the pad and the shoe gages, which have been previously adjusted relatively to the sole gages, are located properly and locked to position the shoe relatively to the sole. Reverse movement of the bell-crank lever 192 will first release the cam 184 and then positively return the gages to their initial positions away from the shoe bottom. As stated above, the gages are not confined heightwise in the guideways but are free to ride

over the surface of the pad during their operative movement.

All four of the individual sets of gage mechanisms 164 are connected to bell-crank levers 192 in the manner indicated above, and these levers are actuated simultaneously to move the gages toward and from operative position by two arms 200 (Figs. 4 and 16) fixed to a shaft 202 rotatably mounted in a boss on the right-hand wall of the frame, the arms extending upwardly and rearwardly at opposite sides of this wall. Each arm 200 (Fig. 16) is provided with bosses 204 having tapered sockets 205 into the lower ends of which extend screws 206. Resting loosely against the upper ends of the screws are upwardly extending rods 208 the upper ends of which are pivotally connected to the lower arms of the bell-crank levers 192 (Fig. 11). The screws 206 provide means for varying the initial positions of the bell-crank levers to position the sole and shoe gages relatively to each other in accordance with the shape of the shoe to be operated upon. Each rod 208 is normally maintained in engagement with the end of its screw 206 by a tension spring 210 connected to the arm 200 and to the lower arm of the bell-crank lever 192. This arrangement causes the arms 200, when rotated with the shaft 202 in a clockwise direction, as viewed in Fig. 4, to swing the bell-crank levers through the action of the springs 210 and thereby to move the gages yieldingly toward the sole on the pad. When the sole gages 166 contact with the edge faces of the sole and are locked, further movement of the arms 200 stretches the springs 210 and causes the rods 35 208 to leave the screws 206, thereby permitting the arms 200 to be swung a predetermined distance for every sole and shoe. In returning the gages, reverse movement of the arms 200 permits the springs 210 to contract, thereby bringing the rods 208 into engagement with the screws 206 after which the bell-crank levers 192 swing outwardly to move the gage mechanisms positively into inoperative positions.

The particular type of gage mechanism disclosed herein is especially advantageous when operating on relatively thin soles. The tension spring 198 is so light that the gages are very sensitive and very little resistance of the sole on the gages 166 will cause them to become locked almost instantly, thereby insuring accuracy in operation and preventing rolling or curling of the edges of the sole margins. Moreover, the guideways 161 (Fig. 2) are integral with the fixed cover plate 154 so that the gages are relatively close to the points of contact with the sole thereby tending to eliminate springing of the gage members when the shoe is inserted between the locked shoe gages as might happen if the gages were unconfined and free to be wedged apart. Another advantage is the manner of locking the gages by the cam 184 since it will be readily seen that any increased pressure on the front ends of the gages as, for example, by introducing the shoe between them, will tend to lock the gages even more firmly in the guideways. The positive retraction of the gages, which takes place before hydraulic pressure is applied as will be later explained, eliminates any danger of scarring the shoe upper during the pressure-apply-70 ing operation.

The arms 200 for the right-hand unit 14 of the machine are swung about their axis 202 to move the gages against the sole by a cam 212 (Figs. 4 and 16) pivoted on a pin 214 mounted

12 which supports the right-hand unit 14. The cam 212 has an integral arm 216 projecting downwardly therefrom and this arm is pivotally connected to a treadle rod 218 which, in turn, is pivotally connected at its lower end by a pin 219 5 (Figs. 1 and 18) to an upwardly extending arm 220 formed on a gage operating treadle 222. The inner arm 200 (Fig. 16) is provided at its central portion with a roll 224 which rides on the lower surface of the cam 212 and is held against the cam by a relatively heavy spring 226 connected at one end to the arm 200 and at its other end to a pin 228 projecting outwardly from the pivot 16 of the yoked arm 14. The treadle 222 is pivoted on a shaft 230 which extends across the full width of the machine and forms the pivot for various other mechanisms later to be described. Depression of the gage treadle 222 rotates the cam 212 in a counterclockwise direction, as viewed in Fig. 16, to move the high part 10 of the cam against the roll 224. This swings the arms 200 downwardly about their axis 202 and thereby operates the mechanism described above and moves the four sets of gage mechanisms simultaneously toward the sole on the pad. 25

Since the gage mechanisms become locked upon engagement with the edge face of the sole and are maintained in locked position until after a shoe has been mounted on the sole and supported thereon by further mechanism hereinafter 30 to be described, it is necessary that the gage treadle 222 be maintained in a depressed position until the operations referred to have been completed. Accordingly, means is provided for automatically locking the gage treadle in its depressed position after it has brought the gage mechanisms into engagement with the sole. This means comprises a bell-crank lever 231 (Fig. 18) pivoted to the gage treadle on a pin 232 and having a forwardly extending arm in position to 40 be engaged by the operator's foot. An upwardly extending arm 234 of the bell-crank lever is pivotally connected to a rearwardly extending link 236 the inner end of which is pivotally connected to a downwardly projecting lever 238 fulcrumed 45 on a pin 240 mounted in a projection 242 extending rearwardly from the pivot 230 of the gage treadle. The lower end of the lever 238 carries a pin 245 adapted to ride over and engage the upper end of a screw 244 mounted in a boss 50 in the base of the machine when the treadle is depressed to its lowest position. A tension spring 246, connected to the treadle and to the upper arm 234 of the bell-crank lever 231, tends normally to urge that lever in a counterclockwise 55 direction, as viewed in Fig. 18, and thus to rotate the lever 238 in the same direction about its fulcrum 240 to cause the pin 245 to snap over the screw 244 when the treadle is depressed.

If it is desired to release the gage treadle 222 60 in order to retract the gages from the sole before the shoe is mounted thereon, the operator may do so by depressing the forward arm of the bell-crank lever 231 which will remove the pin 245 from the top of the screw 244 and thus permit the gage treadle to return to its elevated position. In the normal operation of the machine, however, release of the gage treadle 222 is effected automatically at a predetermined time in the cycle of the machine by mechanism here- 70 inafter to be described.

The open or retracted position of all the gage mechanisms 164 is determined by a fixed stop 248 (Figs. 1, 4 and 5) in the form of a curved bar screwed to the rear portion of the cover plate 75

154 and having its end portions overlapping the guideways 161 in the rear projections 162 which carry the gage members that operate on the tip line of sole and shoe, this bar having an 5 inner facing of leather or similar material to take the shock of the returning gages. Since all four sets of gages are interconnected for simultaneous operation, retracting movement of the bell-crank levers 192 for the forward or ball line 10 gages will be arrested when the tip line gages contact the stop 268.

As indicated above, after the sole has been located on the pad and the forepart gages have been locked in position against the edge face of the 15 sole, the shoe to which the sole is to be attached is mounted on the forepart of the sole in the position determined by the locked shoe gages 172, these gages having been previously adjusted to produce the required sole extension relatively to 20 the shoe button. The forepart of the shoe is then pressed against the sole by preliminary pressure of about 20 or 30 pounds to the square inch and is held in such position throughout the rest of the pressure-applying operation, thereby 25 permitting the operator to release his grip on the shoe to operate other mechanisms associated with this right-hand station of the machine.

The means for pressing the forepart of the shoe against the sole and for holding it in that 30 position during subsequent operations comprises a forepart holdown lever 250 (Figs. 4 and 5) having downwardly extending ears 252 formed integrally with its central portion whereby it is pivotally connected to the frame on a pin 254. 35 The forward end of the forepart holdown lever has mounted thereon, for sliding movement lengthwise of the lever, a shoe engaging abutment 256. This abutment comprises a rubber pad 258 shaped to engage the forepart of the 40 shoe and covered with leather or similar material 260. The abutment is adjustably mounted in a slot 261 formed in a carrier member 262, the slot 261 extending at a slight angle to the median line of the pad and being inclined relatively to 45 the top surface thereof. The carrier member 262 itself is mounted for sliding movement transversely of the pad in a T-slot 264 formed in the lower side of a slide member 266 having opposite side portions which embrace the end of the lever 50 250 and one of which has a projection or key 268 formed thereon and arranged to enter a slot in the lever 250. The slide 266 is clamped in adjusted position on the lever 250 by a screw having a wing nut 270 on its outer end and a 55 stop screw 269 is provided on the forward end of the lever 250 for limiting movement of the slide in that direction. These angular, lateral and longitudinal adjustments permit the abutment 256 to be positioned properly for engaging 60 the forepart of a shoe on the pad regardless of its size or shape.

The lever 250 has a rearwardly and downwardly extending arm 272 (Fig. 4) on the lower end of which is formed a pair of ears 274 through 65 which extends a pin 276 carrying a roll 278 (Figs. 4 and 14). The pin 276 extends inwardly beyond the ears 274 as viewed in Fig. 4, and, when the lever 250 is in the inoperative position shown in Fig. 4, engages a rubber stop 280 fastened by 70 screws in a depression formed in the frame 12. The lever 250 is normally urged into its inoperative position by a compression spring 282 (Fig. 14) surrounding a rod 284 the lower end of which is pivotally connected to a boss 286 on the 75 frame by a pivoted block 288, the upper end of

the rod being pivotally connected to the lever 250 below its fulcrum 254. The spring 282 is confined between a head on the rod and the block 288 and tends normally to urge the lever 250 rearwardly toward the stop 280.

A cam member 290 for operating the lever 250 is pivotally mounted on the frame on a stud 292 located some distance below the lever 250. The upper portion of the cam 290 is somewhat fan-shaped and has an edge face 291 which engages 10 the roll 278. The right-hand side of the edge face of the cam forms a relatively steep curve terminating at the high part of the cam which part is located substantially at right angles to the steep portion and rises gradually from the 15 pivot 292 so that as the roll rides along the high part the pressure on the forepart of the shoe gradually increases. The steep face of the cam surface is preferably covered with leather or similar material 294 to reduce the wear on the 20 parts. The cam member 290 has a lower portion 25 in the form of a segment 296 provided on its lower edge with ratchet teeth 298, the arc of the segment being struck from the pivot 292. Loosely pivoted on the forward side of the segmental portion 296 on a pin 300 is an auxiliary 30 cam 302 which hangs downwardly by its own weight and is provided with a foot 303 in position to engage the edge of the segment and to maintain the cam 302 in a predetermined position relatively thereto when the cam is at rest. The operating part of the auxiliary cam 302 comprises a relatively thin plate 307 secured to the pivoted portion 302 by a screw 309 and arranged to overhang a small portion of the 35 segment. A lower edge face 304 on this plate is shaped in a predetermined curve, the purpose of which will be presently explained.

The cam member 290 has pivotally secured thereto below the pivot 292 by a pin 305 a 40 treadle-operated rod 306 the lower end of which is pivotally connected to the upper end of an upwardly inclined arm 308 (Figs. 1, 4, 25, and 28) by a pin 310, the arm 308 being pivoted on the shaft 280 which forms the axis for the gage treadle 222. When the rod 306 is lowered from the position shown in Fig. 4, by actuation of the arm 308 the cam 290 is swung about its pivot into the position shown in Fig. 14, thereby swinging the forepart holdown lever 250 into 50 the position shown in Fig. 5 and causing the abutment 256 to press the forepart of the shoe against the sole mounted on the pad 18. As stated, the high portion of the cam is shaped so that the pressure on the shoe gradually increases as the cam 290 is rotated until sufficient pressure is applied to clamp the forepart of the shoe firmly against the pad.

Pivotally mounted on the shaft 280 adjacent to the upwardly inclined arm 308 is a forepart hold-down treadle 312 (Figs. 25 and 28) which has an inwardly extending arm 314 (Fig. 24) arranged to engage a rectangular projection or stop 316 formed on the base of the machine. The treadle 312 is normally maintained in its elevated position by a compression spring 318 surrounding a rod 320 the lower portion of which is fastened in the arm 314 and the upper end of which slides loosely through a hole formed in a split collar 322 (Figs. 17 and 25) secured by a clamping screw 324 to a fixed horizontal shaft 326 extending inwardly from the base 10 and secured thereto by a nut 328 threaded on a reduced end of the shaft. The spring 318 is confined on the rod 320 between 70 75

the split collar 322 and a collar 329 (Fig. 24) fixed to the lower portion of the rod.

The treadle 312 is depressed once to bring the forepart holdown lever 250 into engagement with the forepart of the shoe and, later in the cycle of the machine, it is depressed again to operate further mechanism which moves the pad supporting bar 82 (Figs. 4 and 14) upwardly to swing the yoked arm 74 about its pivot 76 and thereby to cause the forward pad supporting sections to conform the upper and lower pads to the shank and heel portions of the shoe bottom.

In order that the treadle 312 may be connected to the arm 308 during its first depression to operate the cam 290 and thereby to bring the abutment 256 into engagement with the shoe, and, on its second depression, may be disconnected from the arm 308 and connected to another arm on the shaft 230 which operates the pad conforming mechanism referred to above, the following construction is provided. Adjacent to the hub of the treadle 312 (Figs. 17, 25 and 28) on the shaft 230 is pivotally mounted a rearwardly and upwardly extending lever 338 which is connected to the pad conforming mechanism in a manner to be later described and which has a forward arm 332. The outer end of the arm 332 has slidably mounted therein for movement parallel to the shaft 230 a pin 334, the right-hand end of which, as viewed in Fig. 25, is slabbed off at an angle. The pin 334 carries a small pin 336 which extends upwardly through a slot 338 in the arm 332 and prevents the pin 334 from turning. A torsion spring 340 secured by a screw 342 to the inner portion of the lever 338 extends forwardly and engages the pin 336 and tends to maintain the sliding pin 334 at the right-hand limit of its movement as viewed in Fig. 25.

Intermediate of the opposite ends of the holdown treadle lever 312 and in line with the end of the arm 332 is a boss 344 in which is slidably mounted another pin 346 having a small pin 348 projecting upwardly therefrom into a slot 350 formed in the boss, the pin 348 preventing the pin 346 from turning in the boss. The pin 346 is maintained normally at the right-hand limit of its sliding movement by another torsion spring 352 secured to the treadle lever by a screw 354 and having a forwardly projecting portion which engages the pin 348. Before the treadle 312 has been depressed for the first time the end of the sliding pin 346 extends into a semi-cylindrical recess 356 (Fig. 26) formed in a projection 358 extending upwardly from the inner portion of the treadle-operated arm 308. Consequently, the treadle lever 312 is latched to the arm 308 by the pin 346 during the first depression of the treadle so that the latter is moved downwardly by the treadle. The projection 358 has an inclined surface 360 (Fig. 24) formed thereon just above the recess 356. When the treadle is depressed, locking mechanism, indicated generally in Figs. 4 and 14 by the numeral 362, is operated by the auxiliary cam 302, in a manner to be hereinafter described, to lock the cam 290, the forepart holdown 250, and the arm 308 in their operative positions. The compression spring 318 (Fig. 24), however, upon the release of the treadle 312 returns the treadle immediately to its elevated position. As the treadle rises the sliding pin 346 engages the inclined surface 360 and is cammed rearwardly or to the left, as viewed in Fig. 25, whereupon its opposite end engages the inclined surface on the adjacent end of the sliding pin 334 and forces this pin to the left in the arm 332

against the torsion spring 340. Continued upward movement of the treadle moves the pin 346 past the pin 334 thereby permitting the latter to snap forwardly again under the action of its spring 340, as shown in Fig. 26. The pin 346 upon leaving the inclined surface 360, engages a substantially vertical surface 364 (Fig. 24) on the arm 308 which holds the pin in its inner position in the boss 344 so that its left-hand portion overlies an adjacent portion of the pin 334. In this way the treadle lever 312 becomes automatically latched to the forward arm 332 of the lever 330 which operates the slide bar 82 and pad operating mechanism hereinbefore referred to. The unlatching of the treadle lever 312 from the arm 332 and the return of the pin 346 into the recess 356 in the arm 308 takes place automatically during the elevation of the treadle 312 after its second depression in a manner to be described later.

The forepart holdown locking mechanism 362, referred to above, is best illustrated in Figs. 4, 14 and 15. Pivotally mounted on a stud 366, fixed in the frame 12 below the cam member 290, is a short lever 368 having a forked upper end which is pivotally connected by a pin 370 (Fig. 14) to another lever 372 pivotally secured at its central portion to a link 374 by a pin 375, the link 374 being pivoted in turn on a stud 376 mounted in the frame. The levers 368, 372 form the links of a toggle the upper link 372 of which can move bodily in an upwardly and forwardly direction when the toggle is straightened, owing to its pivotal connection to the link 374. When the toggle is broken, as shown in Fig. 4, a projection on the upper side of the lever 372 engages a stop on the link 374, thereby limiting the breaking movement of the toggle. The straightened position of the toggle is determined by a projection 378 (Fig. 14) on the upper link 372 which engages a surface 380 formed on the forked portion of the lower link 368. The pivot pin 375 also supports a pair of pawls 382, 384 (Figs. 14 and 15) the outer ends of which are normally held against a fixed stop pin 386 in the frame by tension springs 388 secured at their upper ends to the pawls and at their other ends to a pin 390 mounted in the frame. The pawls 382, 384 have secured respectively to their upper portions hardened steel plates 392, 394 which are offset relatively to each other and form teeth for engaging the teeth 298 on the periphery of the segmental portion 296 of the cam 290. The link 372 carries on its upper end a small roll 396 having a groove in its periphery adapted to be engaged by the thin edge face 304 of the loosely pivoted auxiliary cam 302.

When the forepart holdown cam 290 is rotated about its pivot 292 in a clockwise direction, as viewed in Fig. 4, the portion 307 of auxiliary cam 302 engages the grooved roll 396 and straightens the toggle 368, 372, thereby increasing the length of the toggle from the fixed pivot 366 and moving the teeth of the pawls 382, 384 into such a position that they will be engaged by the teeth 298 on the segmental portion 296 of the cam 290 but will ride over these teeth through the yield of the springs 388 as the cam is rotated in a clockwise direction. When the abutment 256 on the holdown member 250 has been pressed against the forepart of the shoe by the first depression of the holdown treadle 312, the tooth on one of the pawls 382, 384 engages a tooth on the segmental portion of the cam and locks the cam in its operated position thereby locking the

abutment 256 against the forepart of the shoe, the holdown treadle 312 returning to its elevated position through the spring 318, as previously described, while the treadle-operated arm 5 308 remains in its lowered position.

The arm 308 has pivotally secured to its upper end a small rod 398 (Figs. 4 and 17) which extends rearwardly and is connected at its other end to a relatively heavy spring 400, the opposite 10 end of which is connected by a pin 402 to the pad operating lever 330. The spring 400 tends normally to assist in urging the arm 308 into its elevated position so that the rod 398 connected thereto will urge the cam 290 in a counterclockwise direction to insure that one of the teeth on the two pawls will engage a tooth on the segmental portion of the cam 290 and thereby 15 lock the holdown mechanism in its operated position.

20 The lower toggle link 368 extends rearwardly of its pivot 366 and is bifurcated as shown in Fig. 14 to form ears 404. A screw 403 is threaded into the lower portion of the link and extends downwardly between the ears. This arrangement is 25 provided for automatically breaking the toggle 368, 372 to unlock the holdown mechanism at a later stage in the operation of the machine and accordingly will be described hereinafter in connection with the mechanism which effects the 30 automatic release of this mechanism and various other mechanisms of the machine.

The movable mask plate 160 (Figs. 5, 9 and 11) hereinbefore referred to as being slidably mounted between the fixed mask plate 156 and the 35 cover plate 154 at the forepart of the pad, is arranged to slide longitudinally of the pad in the straight recess or guideway 158 (Fig. 9) as the forepart holdown member 250 is moved into and out of operative position. The inner edge 40 face of the mask plate 160, like the plates 154, 156, is shaped to conform substantially to the forepart of a shoe bottom and its forward end portions are cut away at 157 to provide clearance for the ball line positioning gages. The mask 45 plate 160 has formed integrally with its central portion two upwardly and rearwardly projecting tongues 402 (Figs. 5 and 6) upon which are formed upstanding ears 404 connected by a cross piece 406. Rotatably mounted in the upper ends of 50 the ears 404 is a pin 408 and secured thereto by a tapered pin 410 is a downwardly extending link 412. Pivotally secured to the lower end of the link 412 on a pin 413 is a forwardly extending finger 414 the forward end of which projects 55 downwardly and rests of its own weight on the surface of the pad 18, as shown in Figs. 5 and 6. Also mounted on the pivot pin 408 by ears which straddle the link 412 is a rearwardly inclined link 416 having another set of ears at its opposite end between which is pivotally secured by a pin 418, a third link 420. The link 420 is provided with a longitudinal slot 422 which engages a transverse pin 424 mounted in opposite side 60 walls of the holdown lever 250. The links 416, 420 form a toggle between the holdown lever 250 and the movable mask plate 160. A torsion spring 426 (Fig. 5) is mounted on the rotatable pin 408, one end of the spring being secured in the head of the pin and the other end bearing 65 against the pin 418. When the mechanism is in its inoperative position, as shown in Fig. 6, with the holdown lever 250 elevated and the mask plate 160 retracted, the toggle 416, 420 is straight, this position being determined by the engagement 70 of oppositely disposed surfaces on the two toggle 75

links. At that time the link 412 is located substantially at right angles to the surface of the pad and the finger 414 is in a forward position relatively to the mask plate 160.

As the holdown lever 250 is swung forwardly 5 and downwardly into engagement with the shoe, the pin 424 rides along the slot 422 in the link 420 and, upon engagement with the opposite end of the slot, moves the toggle and mask plate forwardly of the machine or toward the heel end of 10 the pad 18. This movement continues until the forward end of the finger 414 engages the edge of the front end of the sole on the pad, at which time the forward movement of the finger 414 is arrested and the link 412 is swung in a counterclockwise direction, as viewed in Fig. 6, until it engages a cross portion of the link 416 between the ears and breaks the toggle. Continued rotation of the holdown lever 250 about its pivot 15 254 causes the toggle to break further by the above action thereby increasing the tension on the torsion spring 426. When sufficient tension has been put on the spring, the latter causes the pin 408, to which it is secured, to turn in the ears 404, thereby swinging the link 412, which is pinned 20 to the pin 408, in a forward direction relatively to the pad and moving the finger 414 quickly away from the front edge of the sole which it has been engaging during the above action. In this way the mask plate 160 is moved forwardly over 30 the pad into a predetermined position relatively to the edge face of the sole, this position being the same for all soles, regardless of their size or shape, so that substantially the same amount of pad surface will be exposed between the sole edge 35 and the mask plate regardless of the size or shape of the sole being operated upon. The positioning finger 414 is then automatically withdrawn from engagement with the front end of the sole to insure that the finger will not be in a position to 40 catch on the front end of the sole when pressure is relieved on the shoe and the shoe is being removed from the pad since this might have a tendency to loosen the attachment of the forward end of the sole to the shoe bottom. When the 45 forepart holdown lever 250 is returned to inoperative position by release of the locking mechanism 362, the toggle 416, 420 is automatically straightened and the finger 414 moved forwardly 50 into its original position relatively to the inner edge face of the mask plate 160. The finger 414 could, if desired, be made adjustable lengthwise so that the distance the mask plate would move over the pad could be varied thereby changing the amount of pad surface exposed between the 55 sole edge and the mask plate.

The machine is provided at each station with means for supporting the heel portions of the shoe and sole against pressure applied by the pad, which means is also constructed and arranged to shift the heel engaging finger 130 laterally of the pad to position the sole relatively to the heel portion of the shoe bottom. This means comprises a U-shaped heel supporting member 428 (Figs. 1, 4 and 7) provided at its central portion with a rigid foot 430 (Fig. 7) for engaging the top of the last in the shoe and having an outwardly and downwardly curving arm 432 which serves as a handle by which the operator can move the heel support into operative position. 60 The lower end of the curved arm 432 is provided with inwardly extending ears between which is pivotally mounted on a pin 434 a shoe engaging member 436 which is substantially V-shaped as viewed from above and is adapted to embrace 65 70 75

the heel end of the shoe after the foreparts of the shoe and sole have been positioned on the pad by the positioning gages 164 and have been clamped in this position by the forepart hold-down 256. The pin 434 is freely rotatable on the handle 432 and the shoe engaging member 436, which is secured to the pin by a set screw 438, normally hangs by its own weight in a forwardly extending position to engage the shoe, this position being determined by a projection 440 on the member 436 engaging the handle 432 between the ears. The upward swinging movement of the member 436 is limited by a pin 441 mounted therein.

The heel supporting member 428 has laterally extending arms 442 best shown in Fig. 1 which curve downwardly at opposite sides of the pad box and are pivotally connected by pins 444 (Figs. 4 and 7) to the upper ends of downwardly and rearwardly extending bars 446 located at opposite sides of the pad box and rigidly connected to each other at their lower portions by a cross piece 448 having outwardly facing slots 449 in which the bars are bolted. The pivotal movement of the heel supporting member 428 on the pins 444 is limited by smaller pins 450 located in slots formed in the lower ends of its side portions 442 but this movement is sufficient to permit the foot 430 to adjust itself properly to the angle of the top of the last in the shoe.

The lower ends of the bars 446 extend beyond the cross piece 448 and have mounted therein a transverse shaft 452 relatively to which the bars can rotate (Figs. 4, 7, 14 and 20). Inwardly of the bars on the shaft 452 are two upwardly curving arms 454 which are free on the shaft and are interconnected at their upper portion by a transverse rib 456 having secured to its lower side, as viewed in Fig. 14, an inwardly projecting lip 458 adapted to engage the frame 12, as shown in Fig. 4, and to act as a stop for rearward movement of the interconnected arms 454. At their upper ends the arms 454 (Fig. 20) are pivotally connected to fixed studs 460 secured by set screws 461 in the opposite sides of a Y-shaped yoke member 462 having a boss 464 at its central portion through which extends an upwardly and forwardly inclined shaft 466 rotatably supported in a bearing in the frame 12, the yoke member 462 being fastened to the shaft 466 by a taper pin 468.

The yoke member 462 (Figs. 4 and 20) is provided at opposite sides with upwardly extending arms 470 to the upper ends of which is pivotally secured by shoulder studs 472 a forwardly extending guide member 474 which is substantially U-shaped in plan view and has relatively wide side portions which are supported near the forward end of the member by inwardly projecting pins 476 (Figs. 4 and 7) which enter slots 477 formed in the opposite side portions of the forward pad supporting section 60, these side portions being connected at their forward ends by an angle bar cross portion 478. The guide member 474 has a sliding fit between the opposite bars 446, Fig. 20, and the inner surfaces of the side portions engage the opposite edges of the slide plate 104 which carries the sole engaging tongue 130.

Outside the arms 454 the shaft 452 has loosely pivoted thereon a pair of downwardly and rearwardly extending bars 480 (Figs. 4 and 20) which are held on the shaft by collars 482 pinned to the opposite ends thereof. The bars 480 are located at opposite sides of the side wall of the frame which supports the right-hand operating station 75 and are connected at their lower ends to a semi-

cylindrical cross piece 484 (Figs. 20 and 21) having threaded stems 486 projecting from its opposite ends on which the bars 480 are pivotally secured by washers 488 and nuts 490. The cross piece 484 passes through an opening 492 in the frame 12 and, as shown in Fig. 21, is provided with a forwardly projecting shank portion 494 which is rotatably mounted in the lower end of a slide bar 496 mounted for sliding movement at an angle of about 45° in a guideway 498 (Figs. 4 and 14) 10 formed in the outer surface of the side wall of the frame 12, the slide bar being retained in the guideway by a pair of plates 500 secured by screws to the frame and overlapping the guideway. The shank 494 is retained in the slide bar 496 by a pin 502 (Fig. 21) having a drive fit in the slide bar and extending into a circumferential slot 504 in the shank. One side of the shank 494 inwardly of the slot is cut away, as shown at 506, so that the cross piece 484 can be readily removed from 20 the slide bar by turning it until the flat portion of the shank registers with the pin 502.

It will be clear from the foregoing that the entire assembly which supports the heel engaging member 428 is rotatable on the shaft 466 in the frame and the shank 494 of the cross piece 484 and, when permitted to do so, as will be presently explained, the assembly can be rotated by the operator by the handle 432 about these axes which, as shown in Fig. 14, are in alignment with each other. In its inoperative or idle position, however, the mechanism supporting the heel engaging member 428 hangs downwardly away from the pad on the studs 460 which, as stated, are secured in the yoke member 462 by set screws 461. 35 The forward portion of this mechanism namely, the bars 446 which carry the heel engaging member 428, is supported in the position shown in Fig. 4 by a grooved roll 508 (Figs. 1 and 4) rotatably mounted on a shaft 512 journaled in a 40 bracket 514 secured to the frame between the right- and left-hand stations of the machine. The mechanism is prevented from turning laterally of the machine about the aligned axes 466, 494 when in an inoperative position by the engagement of the inner sides of the upper bars 446 with the ends of laterally projecting lugs 516 (Figs. 4 and 20) formed on the forward ends of the opposite sides of the pad supporting arm 74. In moving the heel engaging member 428 and the 50 shoe gage 436 into shoe engaging position, the operator swings the bars upwardly about the shaft 452 by the handle 432 and frees the bars from engagement with the lugs 516, thereby permitting the entire assembly to rotate laterally of the machine about the axes 466, 494. He then moves it upwardly and forwardly over the shoe, the forward movement being permitted by the pivoted arms 454 and the slide bar 496. The arrangement is such that the U-shaped gage 436 can be 55 moved laterally of the pad after the member 428 is over the shoe until the gage has been brought into engagement with the heel portion of the shoe, the foot 430 being located substantially above the center of the gage so that it is then in 60 position to engage the heel portion of the last in the shoe.

As stated above, the side portions of the guide member 474 which slidingly engage the inner surfaces of the bars 446 (Fig. 20), are wide enough 70 to engage the opposite edges of the sliding plate 104 which carries the sole engaging tongue 130. Accordingly, when the shoe gage 436 is shifted laterally of the pad to engage the shoe, the guide member 474 will move the plate and tongue 75

(which is then engaging the heel portion of the sole by the pin 438) and thus shift the heel portion of the sole laterally to bring it into proper alignment with the heel portion of the shoe. 5 Consequently, when the shoe gage 436 is moved into engagement with the shoe and the heel supporting foot 430 is moved into engagement with the last, the heel portion of the sole will be automatically shifted into the proper lateral position 10 relatively to the corresponding portion of the shoe. As stated above, the forward portion of the guide member 474 is supported by pins 476 mounted therein and riding in slots formed in the opposite sides of the pad supporting section 60. 15 The slots are long enough to permit lateral movement of the guide member in positioning the tongue 130 transversely of the pad as the supporting arms 470 turn with the yoke member 464.

When the heel supporting mechanism is returned automatically to inoperative position in a manner later to be described, the bars 446 drop back against the lugs 516 which are rounded in such a way that the bars slide over the upper sides of the lugs until the bars are again engaging the ends of the lugs. Thus the heel supporting mechanism is returned to a central position 20 relatively to the pad and the heel locating tongue 130 is also centralized by the guide member 474. Consequently, the tongue 130 is always located 25 centrally of the pad when a fresh sole is mounted thereon so that the operator is not obliged to centralize the tongue by eye after operating on a sole and shoe in which, for example, the rear portions were offset or twisted at a considerable angle to their foreparts. 30

The weight of the heel supporting mechanism is sufficient to make it desirable to provide means for offsetting a portion of it and thereby to assist the operator in moving the mechanism into operative position. To this end the left-hand bar 480, as viewed in Fig. 20, is provided with a laterally extending pin 518 to which is connected a relatively heavy spring 520 connected at its upper end to a chain 522 which runs over a pulley 524 rotatably mounted on the fixed stud 460. The 40 upper end of the chain 522 is connected by a connecting member 528 to a pin 526 mounted in the bar 446. The spring and chain arrangement tends to support the lower portion of the heel engaging mechanism and, when the upper part is moved over the shoe, this arrangement also assists in lifting the lower mechanism and sustaining its weight. As a further aid in moving the mechanism into operative position, a torsion spring 530 is provided on the shaft 452, the right-hand end of the spring, as viewed in Fig. 20, being hooked into the hub of one of the arms 454 and its left-hand end bearing against the rigid cross piece 448 (Fig. 7), the spring tending to urge the forward bars 446 into a more nearly vertical position about the shaft 452. Since the springs 520 and 530 tend to move the heel engaging mechanism into its operative position, the weight of the various elements is partially overcome and the manual operation of the mechanism by the operator is greatly facilitated. Fig. 7 shows the heel supporting mechanism engaging a shoe on the pad and indicates how the heel gage 436 embraces the heel portion of the shoe to shift the sole engaging tongue 130 laterally in accordance with the position of that portion of the shoe. 55

The heel supporting and sole positioning mechanism is moved into operative position by the operator before the pad has been moved upwardly

against the shank and heel portions of the shoe bottom and this mechanism is locked in operative position against the shoe so that it will support the latter against the pressure of the pads when the latter are moved against the rear portion of the shoe bottom and also when the pad 40 is inflated to apply the sole laying or attaching pressure. The means for locking the heel supporting mechanism in operative position is associated with the slide bar 496 (Figs. 4 and 14) 10 and is actuated by the operation of the mechanism for moving the rear portion of the pad 18 into engagement with the shank and heel portions of the shoe bottom. Accordingly, the locking means for the heel supporting mechanism will 15 be described after the pad actuating mechanism referred to has been explained.

The slide bar 82, which supports the pad through the yoked arm 14 (Figs. 4, 14, 17 and 18), is mounted for sliding movement substantially at 20 right angles to the plane of the surface of the pad in a guideway 532 formed in the outer side of the frame 12, the bar being confined in the guideway by cover plates 534, 536 which span the guideway and are secured respectively by screws to upper 25 and lower portions of the frame. Pivotally secured to the bar 82 by a pin 538 is a downwardly extending bar 540 having, at its lower end, a long slot 542. The rearwardly extending lever 330 associated with the forepart holdown treadle 30 312 has pivotally secured to its upper end on the pin 402 a member 544 having an upwardly, curved arm provided with ears which straddle the bar 540 and carry a pin 546 which rides in the slot 542. The lever 330 is normally positioned so that 35 the pin 546 engages the upper end of the slot 542, partly by the spring 400 which connects the lever 330 to the treadle arm 308, and partly by other mechanism extending between the member 544 and the lever 330. This latter mechanism 40 comprises a link 548 pivotally connected at its lower end to the lever 330 by a pin 550 and at its upper end to another link 552 by a pin 554. The upper end of the link 552 is pivotally connected by a pin 556 to the lower end of a thrust member 558 mounted for yielding movement in a 45 boss 560 (Figs. 17 and 19) formed on the lower portion of the member 544. The links 548, 552 form a toggle between the lever 330 and the pivoted member 544 and the toggle is normally maintained in a nearly straightened position against a stop screw 562 in the lever by a spring 564 connected at one end to a downwardly extending arm on the toggle link 552 and at its other end to the lever 330. 50

The thrust member 558 (Fig. 19) provides a yield which permits the toggle 548, 552 to assume a straightened position without affecting the position of the pivoted member 544. The shank portion 566 of the thrust member extends through an opening 568 in the boss 560 and has a bushing 570 threaded on its lower end. The bushing has a sliding fit in the opening and is provided with a groove 572 into which extends a pin 574 to prevent the bushing from turning in the opening. 65 The opposite end of the shank 566 carries lock nuts 576 which determine the lower position of the thrust member in the boss and into which position it is constantly urged by a relatively heavy compression spring 578 bearing at one end 70 against the boss and at the other end against the bushing 570.

When the treadle 312 is depressed by the operator, the lever 330 is swung in a counterclockwise direction as viewed in Fig. 4, and, since the toggle 75

548, 552 is at that time straight, the pin 546 forces the bar 82 upwardly to move the slide bar 82 upwardly in the frame and thereby to swing the yoked pad supporting arm 14 about its 5 pivot 76. This movement causes the forward pad supporting sections 52, 60 to adjust themselves about the pivots 54, 58, as described above, to conform themselves to the contour of the bottom surface of the shank and heel portions of the 10 shoe which is then held rigidly against the forepart of the pad by the abutment 256. This action conforms the outer or rear portions of the pads 18 and 40 and the sole mounted thereon to the shape of the shank and heel portions of the 15 shoe bottom. Since the foreparts of the sole and shoe are already under the pressure applied by the hold-down lever 250, it will be seen that the initial or preliminary pressure on the entire shoe bottom is applied progressively from toe to heel 20 thus insuring that the sole will be laid properly against the shank portion of the shoe bottom and eliminating the danger of the shifting of the sole relatively to the shoe after they have been positioned.

25 Since the pad supporting mechanism, including the pivoted sections of the pad box and supporting arms 14, are relatively heavy, further means is provided for assisting the treadle mechanism in moving the slide bar 82 upwardly. This 30 means comprises an arm 580 (Figs. 4 and 14) pivotally connected at its lower end to an upwardly extending link 582 the upper end of which is pivotally connected to the slide bar 82 by a pin 584. The arm 580 is pivoted to the frame on a fixed 35 stud 586 and its hub portion has a flange 588 to which is pivoted by a pin 590 located below the center 586 a rearwardly extending rod 592 slidably supported at its other end in a plate 594 secured to the frame 12. A compression spring 596 40 surrounds the rod 592 and bears at one end against the plate 594 and at its other end against a head on the rod so that the latter tends normally to urge the arm 580 in a clockwise direction, as viewed in Fig. 14, thereby to urge the slide bar 82 upwardly in the slot 532. The action of 45 the arm 580 facilitates upward movement of the slide bar 82 and reduces the force which must be applied to the treadle 312 to move the pad and its supporting mechanism into operative position 50 against the shoe bottom.

It will be obvious from the above that by relatively locating the foreparts of the sole and shoe and clamping them in such position while the shank and heel portions of the sole are not engaged by the shoe bottom and are therefore free to be shifted laterally of the pad to bring these 55 portions into proper alignment with corresponding portions of the shoe bottom, certain advantages result which cannot be obtained when the full length of the shoe is resting on the sole during the positioning operation either by its own weight or, as is often the case, by the manual pressure of an operator who is holding the shoe in place while the positioning gages are operating. Among the advantages of this mode of 60 operation are the accurate alignment of the entire sole with the shoe bottom without forcing the sole to creep on the shoe bottom while it is contacting therewith and also the fact that no curve 65 or twist will be created at the ball line or in the shank portion of the sole due to pressure against the sole from the shoe.

Moreover, the foreparts of the sole and shoe are positioned without any creeping action relatively 70 to each other because the shoe is placed directly

on the sole from above after the gages have been properly positioned. The positioning of the sole and shoe by the present machine is also more accurate than by other methods because, after the sole is positioned, it is pressed into actual engagement with the shoe bottom progressively from the forepart to the heel so that there is no danger of the sole shifting longitudinally of the shoe as would be apt to happen if the engagement of the forepart and heel portions of the sole and 10 shoe were effected by pressure applied simultaneously with or before pressure was applied to their shank portions to bring the parts into complete engagement.

When the pad and its supporting mechanism 15 meet resistance from the shoe, upward movement of the slide bar 82 and its actuating mechanism ceases. Further depression of the treadle 312, however, swings the lever 330 further upwardly about the shaft 230 so that the member 20 544 then pivots about a fixed axis formed by the pin 546 in the upper end of the slot 542, thus breaking the toggle 548, 552, as shown in Fig. 28, and permitting the lever 330 to continue to swing upwardly for the full movement of the treadle 25 312. The action of the member 544 upon the breaking of the toggle causes several things to take place substantially simultaneously but, since the first part of the treadle movement actuates the mechanism for locking the heel engaging and 30 positioning members 428, 436, this mechanism will next be described.

Pivoted on a stud 598 (Fig. 14) secured in the frame 12 is a bell-crank lever 600 having a lower arm 602 which extends forwardly 35 and downwardly and normally engages the pin 538 which connects the pad elevating bar 540 to the slide bar 82. The upper arm of the bell-crank lever 600 has pivotally connected thereto a rod 604 which extends upwardly through a hole 40 in a flange 606 projecting from a cover plate 608 (Fig. 4) secured by screws to a rectangular projection 610 (Fig. 14) formed on the side wall of the frame and provided with an upwardly and rearwardly inclined slot or guideway 612 located at right angles to the guideway 498. The rod 604 is threaded into a slide member 614 mounted in the guideway 612 and provided at its lower portion with an opening in which is mounted a compression spring 616, the spring bearing 50 at its lower end against the flange 606 and tending to urge the slide upwardly in the guideway. The upper end of the slide 614 is provided with ratchet teeth arranged to engage teeth on the lower edge of an elongated plate 618 fastened to 55 the slide bar 496. When the pin 538 on the bar 82 is moved upwardly in the guideway 532 away from the bell-crank lever 600 the slide 614 is moved upwardly by the spring 616 to bring the teeth on the slide into engagement with those on 60 the bar 496 thereby locking the bar in the guideway 498. Consequently, the heel supporting member 428, which is now engaging the last in the shoe, is locked against further upward movement. Reverse movement of the pad supporting bar 82 and pin 538 will swing the bell-crank lever 600 to withdraw the slide 614 from engagement with the teeth on the slide bar 496 and thus 65 unlock the heel engaging member 428, this action taking place automatically later in the cycle 70 of the machine, as will be described hereinafter.

As the operator continues the second depression of the treadle 312, the yoked arms 14 are swung upwardly about the pivot 76 and the rear portions of the pad sections 52, 60 automatically 75

adjust themselves to the shape of the shoe bottom, thereby conforming the pads 18 and 40 to the shank and heel portions of the shoe in the manner indicated above and applying preliminary pressure to these portions of the shoe bottom. When the pad actuating mechanism meets the resistance of the shoe supported by the member 428, which is now locked in position, the toggle 548, 552 is broken and the pivoted member 544 swings upwardly about the now fixed axis 546 to permit the lever 330 to continue its upward movement through continued depression of the treadle.

Pivottally secured to a lower portion of the pivoted member 544 by a pin 620 is a downwardly extending rod 622 (Figs. 4, 17 and 28) the lower end of which passes through a horizontal stud 624 pivotally mounted in the lower portion of the lever 330. Secured on the lower end of the rod 20 by a nut 626 is an upwardly projecting finger 628 and extending forwardly from the hub portion of the finger, as viewed in Fig. 17, is a small pin 630. The hub of the finger 628 normally engages the stud 624 and is held in this position by the 25 position of the pivoted member 544 when the toggle 548, 552 is in the straightened position shown in Fig. 17. When the toggle is broken, however, as shown in Fig. 28, the rod 622 is lowered relatively to the lever 330 and the hub of 30 the finger 628 leaves the stud 624. The upper end of the finger 628 is arranged to engage the lower arm 632 of a lever 634 pivotally secured on the shaft 326 which carries the collar 322 supporting the spring 318 for returning the treadle 35 312 to inoperative position (Fig. 25). The lever 634 is normally urged in a counterclockwise direction, as viewed in Fig. 17, by a torsion spring 636 (Fig. 25) mounted on the shaft 326 and having one end hooked under the lever 634 and the 40 other end fixed in a collar 638 rigidly secured to the shaft by set screws 640. Consequently, when the finger 628 is lowered away from the stud 624 by downward movement of the rod 622, the lever 634 will be swung by the spring 636 45 about the shaft 326 and move the upper arm of the lever into a more nearly vertical position.

The upper arm of the lever 634 has pivotally secured thereto an upwardly and rearwardly extending rod 642, the upper end of which is secured to a slide member 644 (Fig. 14) mounted for sliding movement in an inclined guideway 646 formed in a projection on the side wall of the frame 12 and covered by the plate 538 which maintains the slide bar 82 in the guideway 532. The upper end of the slide 644 has teeth 648 55 formed thereon which are adapted to engage teeth 548 on the lower edge of the pad supporting bar 82. Upward movement of the rod 642, therefore, moves the slide 644 into locking engagement with the bar 82 to lock the latter in the position into which it has been moved in bringing the pad and its supporting mechanism into operative engagement with the shoe bottom. Reverse movement of the rod 642 (Fig. 17) 60 through the straightening of the toggle 548, 552 will move the finger 628 upwardly to swing the lever 634 in a clockwise direction and withdraw the slide 644 to release the pad supporting mechanism.

In order to prevent the toggle 548, 552 from straightening sufficiently upon release of the treadle 312 after its second depression to cause the finger 628 to withdraw the locking mechanism before pressure is relieved on the shoe, a 70 latch member 650 (Figs. 17 and 28) is pivotally

mounted on the stud 624 to insure that the rod 622 will be held downwardly away from the arm 632 of the lever 634 until all the locked mechanisms are released automatically through the operation of the opposite or left-hand sole laying station of the machine in a manner to be described hereinafter. The latch 650 comprises a U-shaped member having a forwardly extending upper arm 652 with a lower edge face which bears against the small pin 630 and is notched at 10 654 (Fig. 17) for engaging the pin. The latch member is held against the pin 630 by a spring 656 secured at its lower end to a lower portion of the latch and at its upper end to a collar 658 fixed to the rod 622. The latch is provided with 15 a lower arm 660 which is longer than the arm 652 and has a curved end for engaging the base 10 of the machine when the latch is moved bodily downwardly by the descent of the lever 330 upon which it is mounted. When the end of the arm 20 660 of the latch engages the base of the machine its upper arm is raised relatively to the rod 622 to release the pin 630 from the notch 654 and thus to permit the rod to be moved upwardly by the toggle spring 564 as it straightens the toggle 25 548, 552.

When the toggle 548, 552 is broken and, through the operation of the mechanism described above, causes the pad elevating mechanism to become locked in operative position, the shoe is ready to 30 receive laying pressure through inflation of the inflatable pad 40. Before this happens, however, it is desirable to release the locked sole and shoe positioning gages at the forepart of the shoe and to withdraw them from the sole and shoe so that 35 there will be no possibility of scarring the upper through the bulging of the pad upon which the gages are resting. This is accomplished during the second depression of the treadle 312 by a projection 662 (Figs. 17 and 18) extending rearwardly from the hub of the treadle operated lever 330, 332 (Fig. 25) and having a rear edge face with a depression for engaging the pin 245 on the lever 238 which, after the forepart gages have been operated, rests on the end of the vertical screw 244 and locks the gage treadle 222 in 40 operative position. When the holddown treadle 312 is in an elevated position, the depression in the projection 662 is so located that the pin 245 can be moved over the screw 244, as shown in 45 Fig. 18, the projection 662 assisting to hold it in such position. Since, on the first depression of the treadle 312, the latter is not connected to the lever 330, the projection 662 does not move and the pin 245 continues to rest on the screw 244 50 to hold the gages locked. On the second depression of the treadle 312, however, it is latched to the forward arm 332 of the lever 330, as shown in 55 Fig. 26, so that the projection 662 is moved upwardly to cam the pin 245 off the screw 244 and to permit the gage treadle 222 to return to elevated position through the operation of the spring 226 (Fig. 16), thereby positively retracting the positioning gages from the sole and shoe. The timing of the mechanism is such that release of the positioning gages occurs shortly after the toggle 548, 552 breaks and the locking mechanism associated therewith is operated to lock the pad supporting mechanism in operative position. After the positioning gages have been released, 60 the machine is ready to apply the sole laying or attaching pressure to the shoe bottom. This is accomplished by the last part of the second depression of the treadle 312 which movement first 65 "sets" or positions valve mechanism for inflating 70 the shoe. The timing of the mechanism is such that release of the positioning gages occurs shortly after the toggle 548, 552 breaks and the locking mechanism associated therewith is operated to lock the pad supporting mechanism in operative position. After the positioning gages have been released, 75 the machine is ready to apply the sole laying or attaching pressure to the shoe bottom. This is accomplished by the last part of the second depression of the treadle 312 which movement first "sets" or positions valve mechanism for inflating 75

the pad 40 in the right-hand station and for exhausting the pad in the left-hand station as well as effecting the automatic release of all the locked mechanisms on the left-hand station 5 which have been previously operated in the manner described with reference to the right-hand station.

In order to give a clear understanding of the setting of the valve mechanism for inflating the 10 pad 40 of the right-hand station and of the automatic release of the locked mechanisms in the left-hand station corresponding to those on the right-hand station, the description of the automatic release will be made with reference to 15 the mechanisms illustrated on the right-hand station but with the understanding that the description refers to corresponding mechanisms on the left-hand station where the sole and shoe have been under full pressure and are about to 20 be released automatically from the machine upon the application of pressure to the right sole and shoe which are now ready to receive such pressure. Before describing how the last part of the second depression of the treadle 312 positions 25 the valve mechanism for inflating the right-hand pad and for exhausting the left-hand pad, it will be necessary to describe the construction of the valve mechanism and a portion of the mechanism for actuating the same.

30 The valve mechanism for controlling the admission of fluid under pressure, for example water, to the pads 40 is located in the base 10 of the machine and is somewhat similar in construction and operation to valve mechanism disclosed in Letters Patent No. 2,080,037, for improvements in Machines for applying pressure to shoe bottoms, granted May 11, 1937 on an application filed March 23, 1935 in my name. The valve mechanism comprises a valve casing 664 (Figs. 1, 35 27 and 31) containing valve mechanisms for the right- and left-hand stations of the machine, each mechanism, as disclosed in the application referred to, being arranged to admit and exhaust fluid from its corresponding pad by actuating 40 mechanism connected to the casing. The fluid enters the valve casing through an opening 666 (Fig. 27) in the lower portion of a chamber 668 which is common to both valves and from which the fluid passes through either the right- or left- 45 hand valve into its corresponding pad. Since both valves are identical in construction only the right valve shown in section in Fig. 27 will be 50 described in detail.

The upper portion of the chamber 668 extends 55 into the right-hand side of the casing and is closed at the top by a cover plate 670 secured to the casing by screws 672. The lower portion 673 of this cover plate is cylindrical in shape and at its lower end is tapered to form an opening or 60 inlet port 675 through which fluid can pass into a lower chamber 674 having an opening 676 at one side to which a pipe 678 is connected, the pipe extending laterally and rearwardly of the machine and being connected at its rear end by 65 a coupling or elbow 680 (Figs. 4 and 31) to the hose 28 which leads to the right pad 40. Fluid from the central chamber 668 passes into a chamber 682 in the cover 670 through a plurality of holes 684 formed in its upper cylindrical portion. 70 The opening at the lower end of the chamber 682 is closed when a shoe and sole are being mounted on the right-hand station of the machine and the inflatable pad 40 is at that time deflated, as shown in Fig. 5. The corresponding inlet port 75 for the left-hand station is then closed since the

sole and shoe in that station are under pressure but is in a position to be opened by sufficient fluid pressure. The lower chamber 674 extends downwardly through the casing and is enlarged at its lower end, as shown in Fig. 27. Slidably 5 mounted for heightwise movement in the chamber 674 is a slide valve 686. The valve 686 is cylindrical in shape and has annular flanges 688 formed thereon for engaging the wall of the chamber 674 so that the valve 686 will be supported for sliding movement in the chamber. The lower end of the slide valve 686 is enlarged and is cupped to receive washers 690 of felt or other suitable material which are adapted to engage an upwardly projecting flange surrounding an opening 692 at the lower end of the chamber 674 and forming the outlet or exhaust port of the right-hand valve mechanism. When the washers 690 are seated against the flange on the port 692, the outlet valve is closed and no 20 fluid can be exhausted from the chamber 674.

The valve member 686 has a vertical bore 694 in which is mounted a compression spring 696 the upper end of which supports the shank portion of a second slide valve 698 telescopically 25 mounted for vertical movement in the bore 694 and retained therein by the head of a screw 700 which rides in a slot 702 in the outer valve member 686. The valve member 698 has a shoulder 704 which engages the upper end of the outer 30 valve 686 when the two members are pressed together and thereby limits the contracting movement of these members, the spring 696 being compressed under such action. The upper end of the valve member 698 comprises an upwardly facing 35 valve provided with fiber washers 706 which seat against the inlet port 675 and close that port.

Projecting downwardly from the outlet valve 690 is a stem 708 which extends through the exhaust port 692 and is in a position to be engaged 40 by a forwardly extending arm 710 pivotally mounted on a pin 712 extending through ears 714 formed on the lower side of the casing 664. The forward end of the arm 710 is pivotally connected to an upwardly extending rod 716, the 45 upper end of which is pivotally secured by a pin 718 (Fig. 29) to a forwardly curved arm 720 loosely mounted on a transverse shaft 722 rotatably mounted in bearings in the opposite side walls of the frame 12 and extending across the 50 entire machine.

The left-hand valve mechanism (Fig. 27) is likewise provided with a forwardly extending arm 724 arranged to engage a downwardly projecting stem 726 on the lower end of the exhaust 55 valve and the forward end of this arm is pivotally connected to an upwardly extending rod 728 which, at its upper end, is pivotally connected to the outer end of an arm 730 (Fig. 29) extending forwardly from the shaft 722. The arms 720, 730 60 are loosely mounted on the shaft 722 and hang forwardly over another rotatable shaft 732 (Figs. 4 and 29) journaled in the opposite side walls of the frame and carrying mechanism for moving the arms 720, 730 into different positions relatively to each other.

Arm 720 carries a laterally extending roll 734 arranged to engage the edge face of a cam 736 pinned to the shaft 732 and, when the mechanisms are in the positions shown in Figs. 27 and 70 29, the roll 734 is riding on the high part of the cam 736 to hold the arm 720 in an elevated position relatively to the arm 730 and thereby to hold the exhaust port 692 for the right-hand station open and the inlet port 675 closed so that no fluid 75

can enter the pad. The opposite arm 738 is at this time maintained in a lower position relatively to the arm 720 by a roll 738 (Fig. 29) resting in a depression in the edge face of a cam 740 also pinned to the shaft 732. The hub portion of the treadle actuated lever 330 (Fig. 25) for the right-hand station of the machine is provided with a rearwardly extending arm 742 to the outer end of which is pivotally connected an upwardly extending link 744 (Figs. 17 and 25) and the hub portion of the corresponding treadle actuated lever for the left-hand station is likewise provided with a rearwardly extending lever connected at its outer end to a similar link 746 (Figs. 1 and 29). The upper end of the link 744 has a vertical slot 748 which engages a screw 750 threaded into the outer end of an arm 752 extending forwardly from the hub portion of the cam 736, as shown in Fig. 29. When the right-hand station is being operated and the treadle 312 is about to be depressed for the second time, the screw 750 is located at the lower end of the slot 748, the mechanism having been left in this position by the automatic release above referred to through the previous operation of the left-hand station on which a shoe is now receiving pressure. As the treadle 312 of the right-hand station is depressed, the link 744 is elevated to rotate the cam 736 rearwardly, as viewed in Fig. 29, to permit the arm 720 to lower and, through the rod 716, to move the arm 710 (Fig. 27) away from the stem 708 in the valve mechanism, thereby causing the outlet port 692 to close through the action of the spring 686, the inlet valve 675 remaining seated against the valve seat through the telescopic arrangement of the valve but with only such pressure as will permit the valve to open when fluid under pressure enters the chamber 682. In this way the second depression of the treadle 312 positions or "sets" the right-hand valve mechanism so that fluid under pressure will enter the pad 40 associated therewith and no fluid can be exhausted from the outlet port 692.

Since the shaft 732 (Fig. 29) is rotated by the 45 operation of the mechanism just described, the cam 740, which is fixed to the shaft 732 and connected at its outer end to the link 746 by a screw 754 located in a slot 756 in the link 746, will be rotated from the position shown in Fig. 29 until 50 the high portion of the cam engages the roll 738 thereby elevating the arm 730 and rod 728, the slot 756 in the link 746 permitting downward movement of the cam without affecting the position of the link. Consequently, the left-hand valve mechanism is moved from the position shown in Fig. 27 to open the exhaust valve and 55 positively close the inlet valve, thereby exhausting the pressure from the pad in the left-hand station prior to releasing the shoe.

If it is desired to change the position of the valve mechanisms at any time during the operation of the machine and thereby to release all the locked mechanisms of the machine without depressing either of the treadles 312, this may be 60 accomplished by manual means secured to the shaft 732 (Fig. 29) and comprising an upwardly extending arm 758 the upper end of which is pivotally connected to a forwardly extending rod 760 having a handle 762 (Figs. 1, 4 and 29) at its 65 outer end whereby it may be operated to rotate the shaft 732. After the valve mechanisms have become positioned in the manner indicated above by the last part of the second depression of the treadle 312, final movement of the treadle operates the automatic release mechanism for unlock-

ing the various mechanisms on the left-hand station which are now holding the sole and shoe on the pad which is being exhausted. Just before this happens, however, further valve mechanism at the rear of the machine, which supplies fluid under pressure from a reservoir to the valve mechanisms in the casing 664, is actuated to start the supply of fluid under pressure to inflate the pad 40 in the right-hand station, this operation, as stated, taking place during the final downward movement of the treadle 312 which is then released by the operator and is returned to its elevated position by the spring 318 (Fig. 24) without acting further upon the lever 330.

In order to count the number of shoes upon which the machine operates, the shafts 722 and 732 carry an automatic indicating mechanism comprising a curved link 764 (Fig. 29) pivotally connected at its upper end to an arm 766 which is secured to the shaft 722 by a pin 768. The lower end of the curved link 764 is pivotally connected to a downwardly extending arm 770 (Fig. 30) pivotally mounted on the shaft 732 and having a forwardly extending finger 772 which may cooperate in any usual or convenient manner 25 with an indicating device 774 (Figs. 1 and 4) mounted on a casting 718 secured to the base 10 of the machine, the finger 772 causing the indicator to register each time the finger is moved about the shaft 732 in a forwardly direction by 30 opposite movement of the shaft 722 in a manner to be presently described. A tension spring 778, connected at its lower end to the link 764 and at its upper end to a fixed portion of the frame 12, maintains the link 764 and the finger 772 in a 35 retracted position relatively to the indicator when the shaft 722 is in its normal position shown in Fig. 29, this retracted position being determined by a projection 780 (Fig. 30) formed on the lower portion of the link 764 and arranged to engage a 40 collar 782 pinned to the shaft 732, the collar also maintaining the finger 772 against the cam member 740.

The automatic release of all locked mechanisms on the left-hand station takes place, as 45 indicated above, just as the fluid pressure supply mechanism on the right-hand station is operated to inflate the right-hand pad 40 and, since this is accomplished in the same way for either station, the release mechanism illustrated in the 50 drawings for the right-hand station will be described with the understanding that the depression of the treadle 312 on the right-hand station effects the automatic release of the corresponding holdown and pressure-applying mechanisms on 55 the left-hand station where the shoe is now ready to be released.

On the inner portion of the valve positioning arm 720 (Fig. 29) is an upwardly extending boss 784 in which is secured a horizontal stud 786 having pivotally connected to its outer end an upwardly and rearwardly extending bar 788. As shown in Figs. 4 and 14, the bar 788 is formed in two pieces and is adjustable longitudinally by means of a screw and slot arrangement 789. At 65 its upper end the bar 788 extends through a slot (not shown) formed in a laterally extending flange 790 formed on a plate 792 secured to the retaining plate 500 which overlaps the guideway 498. The upper end of the bar has a recess or 70 shoulder 794 formed therein which, when permitted to do so, is arranged to move under and to engage the lower end of the screw 403 which projects downwardly between the ears 401 on the rear portion of the lower link of the toggle 368, 75

372. When the toggle is broken, as shown in Fig. 4, and the forepart holdown lever 250 is in an elevated position, the bar 788 is maintained in a rearwardly inclined position away from the ears 401 by a stop 796 bolted to the slide bar 496 which, as stated above is connected at 486 to the mechanism which supports and operates the heel engaging member 428. The release bar 788 is maintained against the stop 796 by a spring 788 secured to the bar and to the upper confining plate 508 (Fig. 4). After the forepart holdown lever 250 has engaged the shoe and has been locked in position by the straightening of the toggle 388, 372, the heel supporting member 428 is moved over the last into operative position, thereby moving the slide 496 upwardly in the guideway 498 and permitting the bar 788 to swing upwardly about its pivot 786 under the action of the spring 788 to bring the upper end of the bar against the screw 403. The shoulder 794 does not move under the end of the screw 403 at this time, however, but merely rests against the side of the screw until just before the release of the locking mechanism for the forepart holdown 250.
- 26 The valve controlling arm 780 (Fig. 29) of the opposite station is likewise provided with an upwardly extending boss 802 having secured therein a laterally extending stud 804 to the outer end of which is pivoted another upwardly extending lock releasing bar 806 for breaking the toggle of the locking mechanism for the forepart holdown 250 on the left-hand station of the machine, the construction and operation of this bar and the locking mechanism being the same as that of the bar 788 and the right-hand locking mechanism. When the right-hand valve controlling arm 720 is lowered, as described above, by counterclockwise rotation of the cam 736 (as viewed in Fig. 29) through depression of the treadle 312 in "setting" or positioning the valve mechanism in the casing 664 prior to applying pressure to the shoe on the right-hand pad, the lock releasing bar 788 is moved forwardly and downwardly thereby permitting the shoulder thereon to move under the end of the screw 403 through the action of the spring 788. In this way the releasing bar 788 on the right-hand station is positioned for breaking the right-hand toggle and releasing the lock which holds the corresponding forepart holdown lever 250 positively against the forepart of the shoe. It should be remembered that the above action takes place on the right-hand station while the latter is being operated and while the shoe on the left-hand station which is under pressure is about to be automatically released.
- 60 However, the action described above has previously taken place on the left-hand station when that station was being operated and when the valve controlling mechanism was being set by the left-hand treadle 312 to locate the valve mechanism in a reverse position for inflating the left-hand pad 40. Accordingly, the releasing bar 806 for the left-hand station will already be located in toggle breaking position under the screw in the left-hand toggle when the valve mechanism is being positioned for inflating the right-hand pad. As the cam 740 (Fig. 29) for the left-hand station elevates the valve controlling arm 730 during depression of the right-hand treadle 312, the releasing bar 806 is raised against the screw 403 in the left-hand toggle to break that toggle automatically, thereby unlocking the cam 290 which is swung in a counterclockwise direction, as viewed in Fig. 14, under the force of the spring 400 (Figs. 4 and 28) and permits the forepart holdown lever 250 for the left-hand station to swing upwardly under the action of its spring 282.
- 65 Referring now to Figs. 17 and 28, the pivoted member 544 for the right-hand station has a forwardly extending segmental portion 808 which is swung upwardly on an arc by upward movement of the lever 380 after the toggle 548, 552 is broken. This segmental portion is so located that, on the final upward movement of the lever 380, it is in a position to engage an arm 810 (Figs. 28 and 29) secured to the shaft 722 by a set screw 811 and having mounted in its outer end a pin 812 to which is pivotally secured a rod 814. The rod 814, as shown in Figs. 4 and 31, extends rearwardly and is connected at its other end to valve mechanism located at the rear portion of the machine and arranged to supply fluid under pressure to the pads, this mechanism being illustrated in detail in Figs. 31 to 33, inclusive. On the last part of the downward movement of the right-hand treadle 312, the segment 808 engages the arm 810 and moves it into the position shown in broken lines in Fig. 28 after which this arm immediately returns to the position shown in full lines in that figure, this position being determined by the lug 780 on the link 764 (Fig. 30). The arm 810 remains in this inoperative position until operated again by the movement of a similar arm 816 (Fig. 29) secured by a set screw 818 to the opposite end of the shaft 722, the arm 816 being actuated in the same manner by movement of the left-hand segmental member through the depression of the left-hand treadle 312. This movement of the right-hand arm 810 trips the valve mechanism at the rear of the machine to which the rod 814 is connected and starts the inflation of the right-hand pad 40.
- 70 Coincident with the inflation of the pad, the release of tension on the spring 400 connected to the left-hand treadle-operated lever 380, through the elevation of the arm 388 at that station (Fig. 1) and the return of the cam 290 and forepart holdown mechanism to inoperative position, permits the lever 380 at said left-hand station to swing downwardly about the shaft 230 until the lower arm 660 of the latch member 650 (Fig. 28) engages the base of the machine. Such action deflects the upper arm 652 to release the pin 630 from the notch 654 and permits the rod 622 to move upwardly under the action of the toggle spring 584 which now operates to straighten the toggle 548, 552. Upon return of the rod 622 on the left-hand station to a position corresponding to that shown in Fig. 17, the finger 628 on its lower end engages the lower arm 632 of the lever 634 and swings this lever in a clockwise direction to lower the rod 642 and thus to withdraw the slide 644 (Fig. 14) from locking engagement with the pad supporting bar 82, thereby permitting this bar and mechanism associated therewith to slide downwardly in the slot 582, the force of this action being cushioned somewhat by the compression spring 596.
- 75 As the bar 82 moves downwardly the pin 538 thereon engages the arm 602 of the bell-crank lever 600 and rotates that lever in a counterclockwise direction, as viewed in Fig. 14, to withdraw the slide 644 from locking engagement with the bar 496, thereby permitting this bar to return in the guideway 498 to its lower or inoperative position. Since the rear portion of the pad begins to descend before the heel supporting member 428 is released, the U-shaped

heel supporting member 428 will be free to drop forwardly from over the heel portion of the shoe, thereby completely releasing the shoe on the left-hand station. The dropping movement of the heel engaging member 428 will not be too violent by reason of the torsion spring 530 (Figs. 7 and 20) and the descending movement of the entire heel supporting mechanism will be cushioned somewhat by this spring and by the tension spring 520. The shoe may now be removed from the left-hand pad 18 by disengaging the pin 138 in the sole locating finger 130 from the hole in the attached sole. As stated above, this entire releasing action takes place automatically in the left-hand station where the shoe has been under full pressure while the shoe on the right-hand station is being mounted and locked in position prior to receiving the sole laying pressure. In other words, the mechanism on the left-hand station is all returned to an inoperative or idle position by the automatic releasing means just at the time that the right-hand treadle 312 (which effected this release through the left-hand toggle breaking bar 806 Fig. 29) is tripping the fluid pressure supply mechanism at the rear of the machine to send fluid under pressure through the right-hand valve mechanism in the casing 664 which, as stated above, is set to admit fluid to the right-hand pad and thereby to apply sole laying or attaching pressure to the shoe on that pad. The mechanism for supplying fluid under the pressure to the pads and the manner in which it is operated and controlled will now be described.

The valve casing 664, as shown in Fig. 31, is bolted to a depending wall of the base 10 and hangs downwardly into a container 820 supported in the base and into which the valve mechanisms in the casing 664 empty the water exhausted from the pads against a splash pan 821. The pipes 678 for the two pads extend laterally and then rearwardly at each side of the container and connect with the hoses 28 which lead to the pads. The fluid pressure supply mechanism is located behind the container 820 and comprises a reservoir 822 mounted in the base 10 and normally filled nearly to the top with fluid such as water. The fluid is drawn from the reservoir by a rotary pump 824 of any usual type through a pipe 826. The pump 824 is supported on a bracket 828 and is driven by a pulley 830 connected by a belt 832 to a motor 834 (Fig. 4). A switch box 836 for the motor is controlled by buttons 838 (Fig. 1) located at the front of the machine and connected to the switch box by wiring in the usual manner. When the motor is activated the pump draws water from the reservoir through the pipe 826 and forces it through another pipe 840 (Figs. 31 and 32) into a valve mechanism 842 located at the opposite side of the reservoir 822. Before the valve mechanism is tripped to force water into either one of the pads 40, the valve mechanism is positioned so that water entering it through the pipe 840 empties again into the reservoir through a short pipe or by-pass 844.

The valve mechanism 842 is housed in a casing projecting laterally from a supporting plate 846 mounted on one side of the reservoir. The casing has a cylindrical bore 848 (Fig. 32) which communicates at one end with the pipe 840. The opposite end of the bore 848 is plugged by a bushing 850 through which slides the stem 851 of a valve 852 having a fiber washer 854 on its acting face for closing the opening to the pipe 840. The

stem 851 extends through the valve casing and is pivotally connected outside the casing to a link 858 by a pin 856. The other end of the link 858 is pivotally connected by a pin 860 to a substantially horizontal arm 862 pivoted to the supporting plate by a stud 864. The forward end of the arm 862 has a lug 866 formed on the inner side thereof, as viewed in Fig. 32, which carries a screw 868. The screw is in a position to engage the upper edge of the link 858 when the arm 862 is swung downwardly or in a clockwise direction. The link 858 has a boss 870 formed thereon upon which is pivotally mounted on a pin 872 a bell-crank lever 874. The link 858 and the arm 862 form a toggle which may be operated against the force of a tension spring 876 connected at one end to the pin 872 and at the other end to a pin 878 in the plate 846. When the toggle is broken the slide valve 852 is moved rearwardly of the machine or to the left, as viewed in Fig. 32, so that water pumped to the valve mechanism through the pipe 840 empties back into the reservoir through the pipe 844. When the toggle is straight, as illustrated in Fig. 32, the slide valve closes the opening from the pipe 840 and forces the water into an upwardly extending pipe 880 (Fig. 31) which, at its upper end, is provided with elbow 882 which carries a pressure regulating device 884 of any usual construction for controlling the pressure in the pad which is then receiving the fluid. The water passes from the regulating device into a union 886 to which is connected a small pipe 888 which leads to a pressure gage 890 (Figs. 1 and 4) located at the top of the machine. The union 886 is also connected to a forwardly extending pipe 892 through which water passes into the valve casing 664 through the opening 666 (Fig. 27). Accordingly, when the valve member 842 is closed, as shown in Fig. 32, the water under pressure is forced through the pipe 880 into the regulator 884 and thence into the valve mechanisms in the casing 664 which, as described above, cause it to go to one or the other of the pads 40.

The toggle formed by the link 858 and arm 862 is straightened to close the by-pass 844 by forward movement of the rod 814 when the segmental portion 888 (Fig. 28) of the pivoted member 844 engages the arm 810 and swings it upwardly into the position shown in broken lines in that figure. The rod 814 is connected to the arm 862 of the toggle by a block 893 pivoted at 895 on the arm, the rod sliding loosely through the block. After the toggle is broken the rod 814 is returned to the position shown in Fig. 32 through the return of the shaft 722 to its normal position which is determined by the projection 780 on the curved link 764, as hereinbefore described. A spring 894 is provided on the end of the rod 814 for engaging the pivoted block 893 so that the toggle will be straightened by a yielding action to avoid breaking the parts.

When the pressure in the pad reaches a predetermined amount such, for example, as between 80 to 100 pounds to a square inch, the pressure regulating device 884 operates to cause the water which is being forced through the system to be spilled out of the pipe line through a short outlet pipe 896 projecting downwardly from the lower side of the regulator, thereby preventing any further water from passing into the pad. The water spilled out falls into a dipper 898 secured on the outer end of a lever 900 which is pivoted on a screw 902 mounted in a projection 904 extending into the reservoir from the supporting

plate 846. Rearwardly of its pivot, as viewed in Figs. 31 and 32, the lever 900 is pivotally connected by a pin 906 (Fig. 32) between ears 908 formed on the lower end of a vertical rod 910 which is supported for sliding movement in a lug 912 on the plate 846, the lower limit of this sliding movement being determinable by a collar 914 pinned to the rod and arranged to engage the lug 912. A weight 918 is fastened by screws 916 to the upper end of the rod 910 and the weight tends normally to hold the rod in its lower position on the plate. As the water fills the dipper 898 its weight overcomes that of the weight 918 and causes the forward arm of the lever 900 to swing downwardly about the pivot 902. The inner arm of the lever has an enlarged portion 920 thereon which is normally spaced a short distance from the toggle arm 862 when the toggle is straight, as shown in Fig. 32. When the lever 900 is swung downwardly its inner arm engages the arm 862 of the toggle and forces it upwardly to break the toggle with the cooperation of the spring 876. This moves the valve 852 to the left in the chamber 848 and opens the by-pass 844 to cause further water passing through the system to empty back into the reservoir 822. In this way the fluid pressure supply mechanism is operated to close the valve 852 and to cause fluid under pressure to pass into the pad 40 of that station of the machine which is ready to apply pressure to the shoe and sole. The chamber 42 in the pad is thereupon inflated throughout its entire area, as shown in Fig. 7, to apply the sole laying or attaching pressure to the shoe bottom. When this pressure reaches a predetermined amount the regulator 884 operates and the valve 852 is automatically opened again.

The dipper 898 has a plurality of holes 922 in its bottom which are normally covered by a circular baffle plate 924 (Fig. 33) mounted on a pin 926 slidably mounted in a boss formed on the dipper. As the dipper descends the rod 926 engages a fixed plate 928 (Fig. 31) secured to the reservoir, thereby lifting the plate 924 and permitting the water to be expelled from the dipper. After sufficient water has been emptied the weight 918 returns the dipper to the elevated position shown in Fig. 31 so that the toggle 858, 862 can be again straightened by the rod 814 when the pad in the opposite station is ready to be inflated.

In order to insure that the valve 852 will not be open to admit water to either pad if the motor should be started without a shoe on the pad, means is provided on the machine which makes it impossible to turn on the motor switch or button 838 without first breaking the toggle 858, 862 and opening the valve 852. This means comprises a thin plate 930 (Fig. 1) secured to a transverse shaft 932 rotatably mounted in a bracket 934 bolted to the front of the machine, the shaft being provided at its right-hand end with a handle 936. The plate 930 is positioned so that it will cover the starting button 838 for the motor and must be moved out of the way manually by the operator before pressing the button by rotating the shaft 932 by the handle 936. The plate 930 is normally maintained in a position against the switch button by a torsion spring 938 on the shaft 932, one end of the spring being secured in a collar 940 pinned to the shaft and the other end being fastened in the bracket 934.

The handle 936 is connected by a long rod or wire 942 to the bell-crank lever 874 (Fig. 32) pivotally secured on the toggle link 858. This bell-crank lever has an inwardly and laterally ex-

tending arm 944 which is located under a forward portion of the toggle arm 862. When the bell-crank lever 874 is moved in a clockwise direction as viewed in Fig. 32 by the rod 942 the arm 944 engages the toggle arm 862 and breaks the toggle, thereby opening the valve 852. As the water exhausted from the pads gradually fills the container 820 it passes through a chute 946 back into reservoir 822 so that the water in both receptacles is maintained at a fairly even level.

It will be noted from the foregoing that, when the fore-part of the sole A is pressed against the pad 18 by the preliminary pressure exerted against the shoe by the treadle operated holdown lever 250, the sole will sink only a relatively short distance into the forepart of the pad since the sand filled cells in the latter substantially reduce its flexibility. Moreover, when this pressure is being applied the pad 18 is resting on the deflated pad 40 so that there is only the additional compression of the rubber walls of this pad to add to the amount the shoe sinks, these walls, as shown in Fig. 5, being in direct contact with each other at this time. Accordingly, the foreparts of the pads 18 and 40, supported by the rigid section 22, permit the shoe to be sunk only a predetermined distance into the relatively solid wall formed by the pads and this amount is substantially the same for shoes of all sizes because the pad materials will be compressed alike at the portions directly under pressure without affecting or being influenced by portions lying outside such areas.

It has already been pointed out that the mask plate 160 moves over the forepart of the pad an amount determined by the size of the sole thereon so that the edge of the mask plate is always spaced substantially the same distance from the edge of the sole regardless of its size, thereby exposing the same amount of pad surface between the sole and the inner edge of the mask plate. The above constructions acting in conjunction with each other cause the bottom or outer surfaces of all soles to be located a substantially uniform distance below the bottom surface of the mask plate irrespective of the size of the shoe being operated upon. In other words, each sole and shoe is located substantially the same distance from the edge of the mask plate both before and after final pressure is applied to the shoe. This causes every sole to be pressed against the overlasted portion of the shoe upper with substantially the same pressure per unit of area to insure that the sole is firmly attached out to the edge of the shoe bottom. It also causes every shoe regardless of its size to receive substantially the same roll or wrapping action from the upper pad 18 when the lower pad is inflated. Consequently, the soles will be properly stuck to the margins of the shoe bottoms and will have a uniform roll or wrap toward the shoe upper, this roll being only what appears to be suitable for the type of shoe being operated upon. If more or less convexity of the sole is required this can be accomplished by changing the pressure applied by the inflatable pad 40 or, if desired, by varying the initial or preliminary pressure as well as the final pressure so that the distance the shoe sinks below the plane of the mask plate is varied. The same result could also be attained by adjusting the length of the sole engaging finger 414 on the mask plate as indicated above, so that the distance that the mask plate would be located from the edge of the sole could be varied.

Since all shoes are sunk substantially the same distance into the pads by the forepart holdown 75

- members 258 when the lower pad is deflated, and since the pressure in the inflatable pad is controlled and determined automatically by the valve mechanism described above, each sole and shoe 5 will receive pressure the amount of which is automatically guaranteed by the mechanism of the machine and, as stated above, will be substantially the same per unit of area for every shoe operated on regardless of its size or shape.
- 10 In the operation of the machine briefly summarized, the operator, after first relatively adjusting the sole and shoe positioning gages, lifts the tongue 188 and places on the pad 18 of one station, for example, the right-hand station, an 15 outsole A (Fig. 5) having a suitable cement applied to the marginal portion of its inner surface. If the sole is to be merely laid on the shoe bottom the marginal portion of its inner or shoe engaging surface may be coated before the sole is mounted 20 on the pad with a substantially instantaneous cement such, for example, as rubber cement. If the sole is to be permanently attached to the shoe bottom its marginal portion and that of the shoe bottom may be coated with a relatively quick 25 setting permanent cement such as pyroxylin cement or polymerized chloroprene cement, sometimes called "Supergrip." The operator permits the tongue and sole to drop against the pad through the action of the spring 186 and, if necessary, initially adjusts the heel portion of the sole 30 laterally of the pad by the adjusting mechanism 152 (Fig. 20). The slide plate 104 is next moved forwardly or rearwardly of the pad until the sole appears to be located in the proper longitudinal 35 position, the plate being held in the adjusted position by friction and by the torsion springs 102.
- The operator then depresses the gage treadle 222 to bring the sole gages or feelers inwardly to 40 find the edge face of the sole and to position the shoe gages for receiving and locating the forepart of the shoe on the sole. When the sole gages 186 engage the edge face of the sole A the sole and shoe gages automatically lock through the clamping action of the cam 184 against the guide-way 181 and the gage treadle is held in depressed 45 position by the pin 245 of the latch mechanism 234, 238 resting on the screw 244 (Fig. 18). The operator now depresses the forepart holdown treadle 312 which, during its first depression, is 50 latched to the arm 308 (Fig. 25) that is connected by the rod 306 to the forepart holdown cam 290, thereby swinging the lever 250 to move the abutment 256 into engagement with the forepart of the shoe B and apply preliminary pressure and 55 also to clamp the shoe against the pads, as shown in Fig. 5, this action simultaneously operating to adjust the forepart mask plate 160 over the forepart of the pad 18, after which the toggle 416, 420 breaks to withdraw the finger 414 from 60 engagement with the toe end of the sole. After the abutment 256 engages the shoe, the toggle 388, 372 (Fig. 14) is straightened by the pivoted cam 302 to lock the cam 290 in its operative position and thereby to maintain the forepart holdown 65 250 firmly against the shoe. Upon release of the treadle 312 it is returned to elevated position by the spring 318 (Fig. 24) and the slide pin 346 is cammed away from the arm 308 by the inclined surface 360 and moved into position over the pin 334 in the arm 332 of the treadle-operated lever 330, as shown in Fig. 26, thereby latching the treadle 312 to the lever 330 before its second depression. The operator then grasps the handle 432 of the heel positioning and supporting mechanism and, assisted by the springs 520, 530, lifts 70

this upwardly and inwardly over the heel portion of the shoe, thereby releasing this mechanism from engagement with the lugs 516 on the yoked lever 74 so that the entire assembly can be turned laterally about the pivots 466, 494 until the V-shaped shoe gage 436 embraces the heel portion of the shoe, as shown in Fig. 7, this action simultaneously centralizing the heel portion of the sole relatively to the shoe through the guide member 474. In moving the heel supporting 10 member 428 over the shoe, the forepart lock releasing bar 788 is permitted to swing upwardly so that it rests against the screw 403 in the locking toggle 388, 372.

The operator depresses the treadle 312 a second time to swing the lever 330 upwardly and, through the pivoted member 544 and toggle mechanism thereon, to elevate the bar 540 and the pad supporting bar 82 to which it is connected. In this way the shank and heel portions of the 15 pads 18 and 40 are conformed to the corresponding portions of the shoe bottom and the sole A is laid against the shoe bottom progressively from the toe to the heel end of the shoe. As the bar 540 moves upwardly the pin 538 releases the bell-crank lever 680 (Figs. 4 and 14) to operate the lock for the heel supporting mechanism, thereby locking this mechanism against further upward movement so that the pad and sole can be pressed 20 initially against the shoe bottom with considerable pressure by operation of the treadle 312. The resistance of the shoe against the pad-elevating mechanism breaks the toggle 548, 552 as 25 shown in Fig. 28, and causes the pivoted member 544 on the lever 330 to swing about the pin 546 to lower the rod 622 and move the finger 628 30 away from the lower arm of the lever 634. This lever is thereupon rotated in a counterclockwise direction by its torsion spring 636 (Fig. 25) to 35 force the slide 644 (Fig. 14) on the rod 642 into 40 locking engagement with the pad elevating bar 82, thereby locking the pad and its supporting mechanism in operative position against the shoe bottom.

Continued movement of the treadle 312 causes 45 the projection 682 on the treadle (Fig. 18) to cam the pin 245 off the screw 244 to permit the gage treadle 222 to be returned to elevated position by the spring 226 (Fig. 16) and thereby to unlock and withdraw the sole and shoe gages from 50 engagement with the shoe and sole. As the treadle 312 continues to descend the vertical valve operating bar 744 (Fig. 29) is actuated to position the valve mechanisms in the casing 664 in such a manner that water is exhausted from the pad in the left-hand station while the outlet valve for the right-hand station is positively closed and the inlet valve thereof is positioned so that it will 55 open under fluid pressure. In positioning these valve mechanisms the bar 744 also causes the 60 toggle release bar 788 to drop under the screw 403 and thus be in a position to break the toggle and to release the forepart holdown lever when the opposite station is operated. By the same action the corresponding bar 806 (Fig. 29) for the left-hand station breaks the toggle lock for the forepart holdown on that station and automatically 65 releases the holdown. This final downward movement of the treadle 312 also causes the segment 808 on the pivoted member 544 to engage 70 the valve controlling arms 810 and to trip the valve mechanism 842 at the rear of the machine to close the valve 852 and to send fluid under pressure into the valves in the casing 664 and from there into the inflatable pad 40 in the right- 75

hand station, thereby inflating the pad and applying the sole laying or attaching pressure to the sole and shoe. Release of the treadle 312 for the left-hand station by the unlocking of the forepart 5 holddown on that station permits the lever 330 associated with that station to drop somewhat against the tension of its spring 400. When this happens the lower arm 660 of the U-shaped latch strikes the base of the machine and deflects the 10 upper arm 652 to release the pin 630 and permit the rod 622 to move upwardly through the straightening of the toggle 548, 552 by the spring 564. The finger 628 thereupon engages the lever 634 and swings it in a clockwise direction, as 15 viewed in Fig. 28, to withdraw the lock slide 644 (Fig. 14) for the pad supporting mechanism on the left-hand station, thereby permitting this mechanism to descend while the shoe on the right-hand pad is receiving pressure. Descent of 20 the bar 82 in the left-hand station withdraws the lock for the heel supporting member 428 and its associated mechanism by operating the bell-crank lever 600 and permits this mechanism to drop back off the heel end of the shoe and to return by 25 its own weight to idle position. The release of the locked mechanisms on the left-hand station takes place very quickly in the order described and at about the time that the rear valve mechanism is being tripped to supply fluid under pressure to 30 the right-hand pad. Accordingly, the shoe B on the pad will start to receive pressure at about the time that the shoe in the left-hand station is automatically released from the deflated pad in that station. Another shoe and sole are then 35 mounted on the left-hand station and the operations described above are repeated to apply pressure to this shoe and sole and automatically to release the shoe and sole in the right-hand station.

Having thus described my invention, what I 40 claim as new and desire to secure by Letters Patent of the United States is:

1. A machine for applying pressure to shoe bottoms having, in combination, a pad for receiving a shoe, means for pressing the forepart of the shoe against the pad, and treadle-operated means for effecting relative movement of the shoe and pad to bring the central and rear portions of the pad into engagement with the shank and heel portions of the shoe bottom.
2. A machine for applying pressure to shoe bottoms having, in combination, a pad for receiving a shoe, said pad being normally located in a substantially flat position, means movable heightwise relatively to the pad for pressing the forepart of the shoe against the pad, thereby clamping the shoe with its shank and heel portions spaced from the pad, and means for conforming the rear portion of the pad to said shank and heel portions of the shoe bottom.
3. A machine for applying pressure to shoe bottoms having, in combination, a pad for receiving a shoe, said pad being normally supported in a substantially flat position, means for pressing a shoe against one portion of the pad thereby clamping the shoe thereon, means for moving the other portions of the pad heightwise thereof into engagement with the shoe bottom, thereby conforming the pad to the entire shoe bottom irrespective of the shape of the shoe, and means for thereafter effecting relative movement of the pad and shoe to apply pressure to the shoe bottom.
4. A machine for applying pressure to shoe bottoms having, in combination, a relatively flat pad for receiving a shoe, means for clamping

the forepart of the shoe against the pad, thereby holding the shank and heel portions of the shoe bottom spaced from the pad, separate means for engaging the heel portion of the last in the shoe while the shoe is so held and for supporting 5 the shank and heel portions of the shoe bottom against pressure applied thereto, and treadle-operated means for moving the pad into operative engagement with said shank and heel portions of the shoe bottom before substantial pressure is 10 applied thereto irrespective of the shape of the shoe.

5. A machine for applying pressure to shoe bottoms having, in combination, an inflatable pad for receiving a shoe, said pad being normally located in a relatively flat position, means for clamping the forepart of the shoe in pressure receiving relation to said pad, thereby holding the shank and heel portions of the shoe away from the pad, means for effecting relative movement between the pad and the shoe bottom to bring the rear portion of the pad into pressure-applying relation to the shank and heel portions of the shoe bottom without applying substantial pressure to said portions, thereby conforming the 25 pad to the shoe bottom irrespective of the shape of the shoe, and means for inflating the pad to apply pressure to the shoe bottom.

6. A machine for applying pressure to shoe bottoms having, in combination, a pad for receiving a shoe, means for supporting said pad, said means comprising a plurality of members arranged for relative angular movement to conform the pad to the shape of the shoe bottom and being initially located in a relatively flat position, means for clamping the forepart of the shoe against the pad and against a supporting member underlying said forepart, thereby holding the shank and heel portions of the shoe away from the pad, and means independent of said 40 last-named supporting member for effecting relative angular movement of the other supporting members to conform the pad to the shank and heel portions of the shoe irrespective of its shape.

7. A machine for applying pressure to shoe 45 bottoms having, in combination, a pad for receiving a shoe, means for supporting said pad, said means comprising a plurality of members arranged for angular movement relatively to each other to conform the pad to the shape of the 50 shoe bottom and being initially located in a substantially flat plane, means for clamping the forepart of the shoe against the pad thereby holding the shank and heel portions of the shoe spaced from the pad, and a pivoted arm connected to only one of said supporting members for effecting relative angular movement of said members and thereby conforming the rear portion of the pad to the shank and heel portions of the 55 shoe bottom irrespective of the shape of the 60 shoe.

8. A machine for applying pressure to shoe bottoms having, in combination, a pad having a shoe receiving surface initially located in a substantially flat plane, a holddown lever for 65 pressing the forepart of a shoe against the forward portion of said surface thereby supporting the shoe on the pad with its shank and heel portions spaced from said surface, means for moving the rear portions of the pad to bring said 70 surface into engagement with the shank and heel portions of the shoe bottom irrespective of the shape of the shoe, thereby conforming said surface longitudinally to the shape of the entire shoe bottom, and means for thereafter distorting 75

- said surface to apply pressure to the shoe bottom.
9. A machine for applying pressure to shoe bottoms having, in combination, a flexible pad for receiving a sole and shoe, said pad being originally located in a predetermined flat position, a pivoted lever movable over the forepart of the pad for pressing the foreparts of the sole and shoe against the pad, thereby supporting the sole and shoe against displacement relatively to the pad or to each other, and treadle-operated means for moving the rear portion of the pad heightwise of the shoe into engagement with the shoe bottom before substantial pressure is applied thereto, thereby conforming the pad and sole to the shank and heel portions of the shoe bottom.
10. A machine for applying pressure to shoe bottoms having, in combination, a pad having a relatively flat surface for receiving a shoe, means for pressing the forepart of the shoe against said surface while the shank and heel portions of the shoe are free from engagement therewith, and treadle operated means for thereafter moving the rear portion of the pad against the shank and heel portions of the shoe bottom, thereby laying the sole against the shoe bottom progressively from forepart to heel.
11. A machine for applying pressure to shoe bottoms having, in combination, a flexible pad for receiving a sole and shoe, means for normally supporting the pad in a substantially flat condition, said means comprising a stationary forward section and pivoted rear sections, a hold-down lever for pressing the forepart of a shoe against the pad while so supported, thereby clamping the shoe on the pad with its shank and heel portions spaced from the rear portion of the pad, and pivoted means engaging one of said pivoted sections for moving said sections relatively to each other and to said stationary section to bring the rear portion of the pad into operative engagement with the shank and heel portions of the shoe irrespective of its size or shape.
12. A machine for applying pressure to shoe bottoms having, in combination, a flexible pad for receiving a sole and shoe, a fixed member for supporting the forward portion of the pad, members pivoted respectively to the fixed member and to one another for supporting the rear portions of the pad, a swinging arm for supporting the pivoted members normally in the plane of the fixed member, a holdown for clamping the foreparts of a sole and shoe against the forward portion of the pad, thereby supporting them against movement relatively to the pad but with the shank and heel portions of the shoe spaced from the pad, means for swinging said arm about its axis to move the pivoted members toward the shoe, and means for causing the pivoted members to adjust themselves automatically into conformity with the shank and heel portions of the shoe irrespective of its size or shape.
13. A machine for applying pressure to shoe bottoms having, in combination, a pad for receiving a sole and a lasted shoe, said pad normally having a relatively flat work-engaging surface, a holdown lever for pressing the foreparts of the sole and shoe against the forward portion of the pad thereby clamping the shoe on the pad with its shank and heel portions elevated from said work engaging surface, a supporting member for engaging the heel portion of the last in the shoe, and treadle-operated means for moving the rear portion of the work engaging surface of the pad progressively into engagement with the shank and heel portions of the shoe bottom, thereby bringing the corresponding portions of the sole into engagement with the shoe bottom.
14. A machine for applying pressure to shoe bottoms having, in combination, a pad for receiving a sole and shoe, means for initially supporting the pad in a substantially flat position, a hold-down member for clamping the forepart of the shoe against the pad, thereby holding the shank and heel portions of the shoe away from the pad, means for moving the rear portion of the pad into engagement with the shoe bottom, thereby conforming the pad to the longitudinal contour of the shoe bottom irrespective of the shape of the shoe, and means movable in all directions for supporting the heel portion of the shoe during the conforming operation.
15. A machine for applying pressure to shoe bottoms having, in combination, a pad for receiving a sole and shoe, said pad being normally located in a substantially flat position, a hold-down for clamping the forepart of the shoe against the pad thereby holding the shank and heel portions of the shoe spaced from the pad, means for moving the rear portion of the pad against the shank and heel portions of the shoe bottom thereby conforming the pad to the contour of the shoe bottom irrespective of its shape, and means for supporting the heel portion of the shoe against pressure from the pad, said means being pivotally arranged for movement heightwise and longitudinally of the pad and being also arranged for pivotal movement widthwise thereof.
16. A machine for applying pressure to shoe bottoms having, in combination, a pad for receiving a sole and shoe, said pad being normally located in a substantially flat position, a hold-down for clamping the forepart of the shoe against the pad, thereby holding the shank and heel portions of the shoe spaced from the pad, means for moving the rear portion of the pad against the shank and heel portions of the shoe bottom, thereby conforming the pad to the contour of the shoe bottom irrespective of its shape, means movable heightwise and longitudinally of the pad for supporting the heel portion of the shoe against pressure applied by the pad, said means being also movable laterally of the pad for supporting shoes having heel portions located at substantial angles to their foreparts, and means for locking said heel supporting means in operative position.
17. A machine for applying pressure to shoe bottoms having, in combination, a pad for receiving a sole and shoe, said pad normally having a relatively flat work-engaging surface, a hold-down for pressing the foreparts of a sole and shoe against the forward portion of the pad, thereby clamping the sole and shoe on the pad with the shank and heel portions of the shoe spaced from said work engaging surface, a member for supporting the heel portion of the shoe arranged for movement longitudinally of the pad into work-engaging position, and means for locking said heel supporting member in operative position and for moving the rear portion of the pad against the shank and heel portions of the shoe bottom after the heel supporting member has been locked.
18. A machine for applying pressure to shoe bottoms having, in combination, a pad for receiving a sole and shoe, said pad normally having a relatively flat work-engaging surface, a hold-

down for pressing the foreparts of a sole and shoe against the forward portion of the pad, thereby clamping the sole and shoe on the pad with the shank and heel portions of the shoe spaced from said work engaging surface, a member for supporting the heel portion of the shoe arranged for movement longitudinally of the pad into work-engaging position, means for locking the heel supporting member in work-engaging position, and means for moving the rear portion of the pad against the shoe bottom after the heel supporting member has been locked, thereby conforming the pad to the entire shoe bottom.

19. A machine for applying pressure to shoe bottoms having, in combination, a pad normally located in a substantially flat position for receiving a sole and a shoe on a last, a holdown lever for pressing the foreparts of the sole and shoe against the pad while it is so located, thereby clamping the sole and shoe on the pad, a pivoted member movable heightwise and longitudinally of the pad for engaging the last in the shoe and supporting the heel portion of the shoe against pressure, said member being constructed and arranged automatically to adapt itself to the position of the top surface of the last, and treadle-operated means for locking the pivoted supporting member in operative position and for thereafter moving the rear portion of the pad against the shank and heel portions of the shoe bottom, thereby conforming the pad to the shape of the shoe bottom irrespective of its size or shape.

20. A machine for applying pressure to shoe bottoms having, in combination, a flexible pad for receiving a sole and a lasted shoe, means for normally supporting the pad in a substantially flat position longitudinally, said means comprising a stationary forward section and relatively movable rear sections, a pivoted arm for engaging the rear sections and holding them in a predetermined initial position, a bar for supporting said arm, a holdown lever for pressing the foreparts of the sole and shoe against the pad and thereby clamping them thereon with the shank and heel portions of the shoe spaced from the pad, means for locking said lever, a heel supporting member movable heightwise and longitudinally of the pad into position over the shoe for engaging the last therein, means for moving the supporting bar heightwise of the shoe to bring the pad into engagement with the shank and heel portions thereof, thereby re-positioning the movable sections and conforming the pad to the shank and heel portions of the shoe bottom irrespective of its size or shape, and means actuated by movement of the supporting bar toward operative position for locking the heel supporting member against movement heightwise of the shoe before the pad is brought into engagement with the shank and heel portions of the shoe bottom.

21. A machine for applying pressure to shoe bottoms having, in combination, an inflatable pad for applying pressure to a shoe, means for pressing the forepart of the shoe bottom toward the pad and thereby clamping said forepart in pressure-receiving position but with the shank and heel portions of the shoe bottom spaced from the pad, treadle-operated means for effecting relative movement between the rear portion of the pad and the shank and heel portions of the shoe bottom thereby bringing said portions into operative relation to each other, and means for inflating the pad to apply pressure to the shoe bottom.

22. A machine for applying pressure to shoe bottoms having, in combination, an inflatable pad for applying pressure to a sole and shoe, means for normally supporting the pad in a substantially flat position, a holdown lever for engaging the foreparts of the sole and shoe and pressing them toward the pad, thereby positioning the shank and heel portions of the shoe bottom a substantial distance from the pad, means for moving the rear portions of the pad heightwise thereof into pressure applying relation to said shank and heel portions irrespective of the shape of the shoe, means for locking said moving means in operative position, and means for inflating the pad to apply pressure to the shank and heel portions of the shoe bottom.

23. A machine for applying pressure to shoe bottoms having, in combination, an inflatable pad for applying pressure to a sole and shoe, means movable into engagement with a shoe resting on the pad for clamping the foreparts of the sole and shoe in pressure receiving relation to the pad and for applying relatively light initial pressure to the entire areas of said foreparts, means for conforming the rear portion of the pad to the shank and heel portions of the shoe bottom irrespective of its size or shape, thereby laying the sole against the shoe bottom and applying light pressure thereto progressively from forepart to heel, and means for inflating the pad to apply additional pressure to the entire shoe bottom.

24. A machine for applying pressure to shoe bottoms having, in combination, an inflatable pad having a relatively shallow chamber for applying pressure to a sole and shoe, a pad box for supporting the pad initially in a relatively flat position, said pad box comprising a stationary section for supporting the forward portion of the pad and pivoted rear sections connected to said stationary section for supporting the shank and heel portions of the pad normally in a plane substantially parallel to that of its forward portion, a holdown lever movable over the forward portion of the pad for clamping the foreparts of a sole and shoe in pressure-receiving position relatively thereto, a last engaging member for supporting the heel portions of the sole and shoe against pressure from the pad, means for effecting relative angular movement of the rear sections heightwise of the shoe to bring the pad into pressure-applying position, thereby conforming it to the shank and heel portions of the shoe bottom, and means for inflating the shallow chamber to apply pressure to the sole and shoe.

25. A machine for applying pressure to shoe bottoms having, in combination, a pad for receiving a sole and shoe, means for holding said pad comprising a stationary section and a plurality of relatively movable sections, means for normally supporting said sections in a substantially flat plane, means for moving said movable sections out of said plane to conform the pad to the portions of the shoe bottom adjacent to said sections irrespective of the shape of the shoe, and means acting upon only one of said sections for initially adjusting said movable sections out of said flat plane before the moving means is operated, thereby reducing the pad conforming movement of said moving means.

26. A machine for applying pressure to shoe bottoms having, in combination, a pad for receiving a sole and shoe, a support for said pad comprising a stationary forward section and relatively movable shank and rear sections, means

for supporting said shank and rear sections normally in a plane parallel to that of the forward section, thereby supporting the pad in a substantially flat position, means for relatively moving said shank and rear sections to conform the pad to corresponding portions of a shoe of any size mounted thereon, and eccentric means independent of said moving means for initially adjusting said shank and rear sections out of the plane in which they are normally supported.

27. A machine for applying pressure to shoe bottoms having, in combination, a pad for receiving a sole and shoe, means for supporting said pad in a substantially flat position, said means comprising a fixed section and a plurality of relatively movable sections normally located in the plane of said fixed section, means for initially adjusting said movable sections out of the plane of the fixed section and toward the shoe bottom, means for moving said movable sections toward the shoe bottom to conform the portions of the pad supported thereby to the contour of the shoe bottom, and means on said moving means independent of said adjusting means for further adjusting said movable sections toward the shoe bottom thereby substantially reducing the pad conforming movement of said moving means.

28. A machine for applying pressure to shoe bottoms having, in combination, a pad for receiving a sole and shoe, a support for said pad comprising a stationary forward section and shank and heel sections pivoted to said forward section and movable relatively thereto, a swinging arm for supporting said shank and heel sections normally in a plane parallel to the plane of the forward section, a slide bar for swinging said arm about its axis to cause the pivoted sections to pivot relatively to each other and to the stationary section to conform the rear portion of the pad to the shank and heel portions of the bottom of a shoe mounted thereon, means for actuating said bar to conform the pad to the shoe bottom irrespective of the shape of the shoe, means carried by the swinging arm for initially adjusting said shank and heel sections out of their normal plane, and means on the slide bar and engaging said arm for further adjusting said sections out of said plane.

29. A machine for applying pressure to shoe bottoms having, in combination, a pad for receiving a sole, gage members yieldingly movable only in straight paths toward and away from a sole placed loosely on the pad for finding the edge face of the sole, and means operated by yielding action of each gage member for locking that gage member separately in its path upon its engagement with the sole.

30. A machine for applying pressure to shoe bottoms having, in combination, a pad for receiving a sole, gage members movable toward and away from a sole placed by an operator on the pad for finding the edge face of the sole, and means operated by contact of each gage member with the sole for locking that gage member against movement away from the sole thereby holding the sole in its original position.

31. A machine for applying pressure to shoe bottoms having, in combination, a pad for receiving a sole, gage members movable relatively to the pad for finding the edge face of a sole placed thereon, means for operating said gage members, and means actuated by said operating means when each gage member contacts

with the sole for locking that gage member against further movement relatively to the sole.

32. A machine for applying pressure to shoe bottoms having, in combination, a pad for receiving a sole, gage members movable relatively to the pad for finding the edge face of a sole placed thereon, means for operating said gage members, and means carried by each gage member and actuated as that gage member finds the edge face of the sole for locking said member against movement away from the sole.

33. A machine for applying pressure to shoe bottoms having, in combination, a pad for receiving a sole, gage members movable relatively to the pad for finding the edge face of a sole placed thereon, means movable a predetermined distance irrespective of the size of the sole for operating said gage members, and means actuated by said operating means as each gage member contacts with the edge face of the sole for locking that gage member against movement away from the sole, said locking means permitting further movement of said operating means as the latter moves the other gage members into engagement with the sole.

34. A machine for applying pressure to shoe bottoms having, in combination, a pad for receiving a sole, gage members for finding a sole wherever it is located on the pad by an operator, means for causing the gage members to move toward and away from the sole in straight paths, and pivoted means having a predetermined swinging movement for operating the gage members yieldingly in said paths so that said members merely contact with the sole without moving it on the pad.

35. A machine for applying pressure to shoe bottoms having, in combination, a pad for receiving a sole, a plurality of gages located at opposite sides of the longitudinal median line of a sole placed loosely on the pad by an operator for finding the opposite edge faces of the sole, and means for moving the gages toward and away from the sole in rectilinear paths located substantially at right angles to said edge faces, said means permitting each gage to stop individually upon contact with the sole.

36. A machine for applying pressure to shoe bottoms having, in combination, a pad for receiving a sole, a plurality of gages for finding the opposite edge faces of a sole located on the pad by an operator, straight guideways in which the gages slide bodily toward and away from the sole, a movable cam for operating the gages in their guideways, and means for allowing each gage to stop upon contact with the sole irrespective of the operative movement of the cam.

37. A machine for applying pressure to shoe bottoms having, in combination, a pad for receiving a sole, a plurality of gages for finding the edge face of a sole positioned on the pad by an operator, means for supporting the gages with their sole engaging ends resting by gravity on the pad, means for moving the gages simultaneously in straight paths toward and away from the sole, and means for locking each gage separately upon its engagement with the sole.

38. A machine for applying pressure to shoe bottoms having, in combination, a pad for receiving a sole, a plurality of gages for finding the opposite edge faces of a sole positioned on the pad by an operator, said gages being constructed and arranged to slide toward and away from the sole in straight paths located substantially at right angles to the edge faces thereof.

5 levers for sliding said gages toward and away from the sole, and yielding connections between the gages and levers for permitting each gage to stop when it contacts with the sole, thereby preventing the gages from curling the edges of the sole.

39. A machine for applying pressure to shoe bottoms having, in combination, a pad for receiving a sole, a plurality of gages for finding the opposite edge faces of a sole located on the pad by an operator, said gages being arranged to slide toward and from the sole in fixed guideways located approximately at right angles to the edge faces of the sole, and means for moving the gages simultaneously in said guideways, said means being constructed and arranged to move the gages toward the sole yieldingly but to retract them from the sole positively.

40. A machine for applying pressure to shoe bottoms having, in combination, a pad for receiving a sole, a plurality of gages for finding the edge of a sole placed on the pad by an operator, said gages being arranged to slide toward and from the sole in guideways with their work engaging ends resting by gravity on the pad, a lever connected to each gage for moving it in its guideway, swinging arms for operating said levers, means for swinging said arms a predetermined amount thereby causing the levers to move the gages simultaneously in the guideways, and connections between said levers and said arms constructed and arranged to cause each lever to operate its gage until the gage contacts with the sole and then to yield to permit the gage to stop and the arm associated therewith to swing its full distance.

41. A machine for applying pressure to shoe bottoms having, in combination, a pad for receiving a sole, a plurality of gages for finding the edge of a sole located on the pad by an operator, said gages being arranged to slide lengthwise toward and from the sole in guideways, a lever connected to each gage for moving it in its guideway, swinging arms for operating said levers, means for swinging said arms a predetermined distance in actuating said levers, locking means carried by each gage, connections between each gage and its lever for operating the locking means when movement of the gage toward the sole is arrested by engagement with the sole, thereby locking the gage in operative position, and connections between the levers and the swinging arms constructed and arranged to permit the arms to swing their full distance after the gages are locked, said connections operating on reverse movement of the arms to withdraw the gages positively to inoperative position.

42. A machine for applying pressure to shoe bottoms having, in combination, a pad for receiving a sole, a plurality of gages for finding the edge face of a sole located on the pad by an operator, a lever for moving each of said gages toward and away from the sole, connections between each lever and its gage for permitting the movement of the gage to stop upon engagement with the sole, swinging arms for operating said levers, means for swinging said arms a predetermined amount, and connections between the arms and each lever constructed and arranged to yield after the gage operated by that lever engages the sole, thereby permitting the arm to swing its full stroke, said connections operating without yielding action when the lever is returning the gage to its inoperative position.

43. A machine for applying pressure to shoe

bottoms having, in combination, a pad for receiving a sole, a plurality of gages for finding the edge face of a sole placed on the pad by an operator, levers individual to each gage for moving it toward and away from the sole, and mechanism between each gage and its operating lever for locking that gage against further movement upon its engagement with the sole.

44. A machine for applying pressure to shoe bottoms having, in combination, a pad for receiving a sole, a plurality of gages for finding the edge face of a sole located on the pad by an operator, an actuating lever connected to each gage for moving it toward and away from the sole, means for operating all of said levers simultaneously, and means associated with each gage and lever for permitting the gage to stop upon engagement with the sole while the actuating lever continues its operative movement.

45. A machine for applying pressure to shoe bottoms having, in combination, a pad for receiving a sole, a plurality of gages for finding the edge face of a sole located on the pad by an operator, means for causing the gages to travel in predetermined paths toward and away from the sole, a lever for moving each gage in its path, yielding connections between the gage and lever permitting each gage to stop individually upon engagement with the sole while the lever continues its actuating movement, and means operated by the continued movement of the lever for locking the gage against movement away from the sole.

46. A machine for applying pressure to shoe bottoms having, in combination, a pad for receiving a sole, a plurality of gages for finding the edge face of a sole placed on the pad by an operator, said gages being mounted for sliding movement toward and away from the sole in guideways located substantially at right angles to the edge of the sole, cams carried by the gages for locking them in their guideways, levers for moving the gages in said guideways, and mechanism between the cams and the levers whereby the gages are first moved into engagement with the sole and the cams are then operated to lock the gages in said guideways.

47. A machine for applying pressure to shoe bottoms having, in combination, a pad for receiving a sole, a plurality of gages for finding the edge face of a sole placed on the pad by an operator, said gages being arranged for sliding movement toward and from the sole in guideways, a cam carried by each gage for binding it against movement in its guideway, a link connected to the cam, a lever connected to the link, means for operating the lever to move the gage in the guideway, and a spring extending between the lever and the link, said spring being of such strength that it holds the cam free from the guideway while the lever is moving the gage toward the sole and, upon contact of the gage with the sole, yields so that further movement of the lever operates the cam without moving the gage and thus binds the gage against the guideway.

48. A machine for applying pressure to shoe bottoms having, in combination, a pad for receiving a sole and shoe, a plurality of gage members for finding the edge face of a sole placed on the pad by an operator, said gages being arranged to move in straight paths toward and away from the sole and with their inner ends resting by gravity on the pad, a shoe gage carried by each sole gage, and means operated by en-

5 engagement of each sole gage with the sole for locking that sole gage and its shoe gage against further movement in the guideway, thereby holding the sole in its original position on the pad and determining the position of the shoe relatively to the sole.

10 49. A machine for applying pressure to shoe bottoms having, in combination, a pad for receiving a sole and shoe, a plurality of gage members for finding the edge face of a sole placed on the pad by an operator, said gages being arranged to move in guideways toward and away from the sole and with their inner ends resting by gravity on the pad, a shoe gage carried by each sole gage, a cam carried by each set of sole and shoe gages, a lever for moving each set of gages toward and from the sole, and connections between the lever and the cam whereby the lever first moves the sole gages against the sole and, upon contact of said gages with the sole, ceases to move the gages but actuates the cam to lock the gages in the guideway.

15 50. A machine for applying pressure to shoe bottoms having, in combination, a pad for receiving a sole and shoe, a plurality of gages for finding the edge face of a sole located on the pad by an operator, means for causing said gages to travel in straight paths toward and from the sole, a shoe gage carried by each sole gage, means for adjusting the shoe gage relatively to the sole gage to determine the position of the shoe relatively to the sole, a lever for moving each set of gages toward the sole on the pad, and a cam operated by engagement of each sole gage with the sole for locking the sole and shoe gage against further movement, thereby holding the sole in its original position on the pad and determining the position of the shoe relatively to the sole.

20 51. A machine for applying pressure to shoe bottoms having, in combination, a pad for receiving a sole and shoe, a plurality of gages for finding the edge face of a sole located on the pad by an operator, said gages being movable toward and from the sole in straight guideways, shoe gages carried by the sole gages, means for adjusting each set of sole and shoe gages in the guideways relatively to the other sets, means for adjusting each shoe gage relatively to its sole gage, bell-crank levers for moving each set of gages in its guideway toward and from the sole, arms for operating said levers, means for causing said arms to operate the levers yieldingly when the gages approach the sole and positively when they leave the sole, and means carried by each set of gages for locking it in its guideway independently of the other gages when the sole gage contacts with the sole.

25 52. A machine for applying pressure to shoe bottoms having, in combination, a pad initially located in a flat position for receiving a sole and shoe, gages normally operating by movement toward and away from a sole on the pad for finding the forepart of the sole, shoe gages carried by said sole gages for determining the position of a shoe relatively to the sole, means for clamping the foreparts of the sole and shoe against the pad, thereby holding the shank and heel portions of the shoe away from the pad, and means for moving the rear portion of the pad against the shank and heel portions of the shoe bottom irrespective of the shape of the shoe, thereby conforming the pad to the contour of the shoe bottom.

30 53. A machine for applying pressure to shoe bottoms having, in combination, a relatively flat

pad for receiving a sole and shoe, gages at the forepart of the pad for finding a sole placed on the pad by an operator, shoe gages carried by the sole gages, means operated by engagement of the sole gages with the sole for locking each sole and shoe gage in its operative position, means for pressing the forepart of a shoe against the sole, the shoe being positioned on the sole by the shoe gages, said pressing means clamping the shoe against the pad with its shank and heel portions spaced from the pad, and means for moving the rear portion of the pad against said shank and heel portions irrespective of the shape of the shoe.

35 54. A machine for applying pressure to shoe bottoms having, in combination, a pad having a relatively flat work-engaging surface, gages for finding the edge face of a sole placed on the pad by an operator, shoe gages carried by the sole gages, means for automatically locking the sole gages in work engaging position, thereby determining the position of a shoe relatively to the sole by the location of the shoe gages, means for pressing the forepart of a shoe against the sole in the position determined by said shoe gages, thereby clamping the sole and shoe on the pad with the shank and heel portions of the shoe spaced from the sole, and means for moving the rear portions of the pad into engagement with the shank and heel portions of the shoe bottom irrespective of the shape of the shoe, thereby conforming the pad to the contour of the shoe bottom.

40 55. A machine for applying pressure to shoe bottoms having, in combination, a pad for receiving a sole and shoe, said pad being located normally in a substantially flat position, gage members movable in straight guideways for finding the edge face of the forepart of a sole placed on the pad by an operator, shoe gages carried by said sole gages, means for locking the gages in the guideways upon engagement of the sole gages with the sole, thereby determining the position of the forepart of a shoe relatively to the sole, a lever for pressing the forepart of a shoe against the sole in said predetermined position, thereby clamping the shoe against the pad with its shank and heel portions spaced from corresponding portions of the sole on the pad, and means for conforming the pad to the shank and heel portions of the shoe bottom irrespective of the shape of the shoe, thereby moving the shank and heel portions of the sole against the corresponding portions of the shoe bottom.

45 56. A machine for applying pressure to shoe bottoms having, in combination, a pad having a relatively flat surface for receiving a sole and shoe, gages for finding the edge face of a sole placed on the pad by an operator, shoe gages carried by the sole gages, a holdown lever movable relatively to the pad toward and away from a shoe thereon for pressing the forepart of a shoe against the sole in the position determined by the shoe gages, thereby locating the foreparts of the shoe and sole relatively to each other and clamping the shoe on the pad with its shank and heel portions spaced from the sole, means movable relatively to the clamped shoe for supporting the heel portion of the shoe against pressure applied to its bottom surface, and means for moving the rear portion of the pad into engagement with the shank and heel portions of the shoe bottom irrespective of the shape of the shoe, thereby conforming the sole to the shape of the shank and heel portions of the shoe bottom.

57. A machine for applying pressure to shoe bottoms having, in combination, a pad for receiving a sole and a shoe on a last, gages for finding the edge of a sole placed on the pad by an operator, a shoe gage carried by each sole gage, means for operating said sole and shoe gages, means for locking the sole and shoe gages in operated position, thereby determining the position of the shoe relatively to the sole, means for supporting the forepart of the shoe against pressure applied to the shoe bottom, means movable in all directions for engaging the last in the shoe and supporting the heel portion of the shoe against pressure applied to the shoe bottom, and means for locking the heel supporting means against movement heightwise of the shoe during the pressure-applying operation. 5
58. A machine for applying pressure to shoe bottoms having, in combination, a pad for receiving a sole and a lasted shoe, gages for finding the edge face of the forepart of a sole placed on the pad by an operator, a shoe gage carried by each sole gage, means for locking the sole gages in operative position as they find the edge face of the sole, thereby locking the shoe gages and determining the position of the shoe relatively to the pad, means movable freely in all directions for engaging the last in the shoe irrespective of the position of the heel portion of the shoe relatively to the pad, and means for locking said last engaging means in operative position to support the heel portion of the shoe against pressure applied to its bottom surface. 10
59. A machine for applying pressure to shoe bottoms having, in combination, a pad for receiving a sole and a shoe on a last, gages for finding the edge face of the forepart of a sole placed on the pad by an operator, a shoe gage carried by each sole gage, means for locking the sole and shoe gages in operative position as the sole gages contact with the sole, thereby determining the position of the shoe relatively to the pad, means for supporting the forepart of the shoe against pressure applied to the shoe bottom, and means movable heightwise and longitudinally of the pad for supporting the heel portion of the shoe against pressure applied to its bottom surface, said means being also arranged for pivotal movement laterally of the pad to engage the last in the shoe irrespective of the angle of the heel portion of the shoe relatively to its forepart. 15
60. A machine for applying pressure to shoe bottoms having, in combination, an inflatable pad for applying pressure to a sole and shoe, means for supporting said pad normally in a substantially flat position, sole gages for finding a sole placed on the pad by an operator, a shoe gage carried by each sole gage, means for locking each set of sole and shoe gages individually when the sole gage finds the edge face of the sole, a holdown member for clamping the forepart of a shoe located between the shoe gages in pressure receiving relation with the pad, the shank and heel portions of the shoe bottom being thereby spaced from the rear portion of the pad, means for supporting the rear portion of the shoe against pressure applied by the pad, means for moving the rear portion of the pad into pressure-applying relation to the shank and heel portions of the shoe bottom, thereby conforming the pad and the sole thereon to the shape of the entire shoe bottom, and means for inflating the pad to apply pressure to the sole and shoe. 20
61. A machine for applying pressure to shoe bottoms having, in combination, a pad for receiving a sole and shoe, a plurality of gages for finding the edge face of a sole placed on the pad by an operator, means for moving the gages into engagement with the sole, means operated by such engagement for locking the gages thereby preventing them from curling the edges of the sole, and means for automatically retracting the gages at a predetermined later point in the operation of the machine. 25
62. A machine for applying pressure to shoe bottoms having, in combination, a pad for applying pressure to a sole and shoe, a plurality of gages for finding the edge face of a sole placed on the pad by an operator, means for moving the gages yieldingly in straight paths to find the edge face of the sole, means for locking the gages in said paths upon engagement with the sole, means for holding a shoe on the sole, and means for automatically releasing the gages before maximum pressure is applied by the pad to the shoe bottom and for retracting the gages positively into idle position. 30
63. A machine for applying pressure to shoe bottoms having, in combination, an inflatable pad for receiving a sole and shoe, a plurality of gages for finding the edge face of a sole placed on the pad by an operator, means for moving the gages into engagement with the sole, means for locking the gages upon such engagement, a lever for holding a shoe against the forepart of the sole, means for supporting the rear portion of the shoe against pressure applied to its bottom surface, means for inflating the pad to apply pressure to said bottom surface, and means for automatically unlocking and withdrawing the gages from the sole before inflation of the pad. 35
64. A machine for applying pressure to shoe bottoms having, in combination, an inflatable pad for receiving a sole and shoe, said pad normally lying in a substantially flat position, gages at the forward portion of the pad for finding the edge face of a sole placed loosely thereon, a shoe gage adjustably mounted on each sole gage, treadle-operated means for simultaneously moving each set of sole and shoe gages in a straight path toward and from the sole, cams actuated by said treadle-operated means upon engagement of each sole gage with the sole for locking that gage against further movement, thereby locking the shoe gage carried by said sole gage, a holdown member for holding the forepart of a shoe introduced between the shoe gages in pressure receiving relation to the pad, thereby clamping the shoe with its shank and heel portions spaced from the pad, means for moving the rear portion of the pad toward said shank and heel portions to bring the pad into pressure-applying relation thereto, thereby conforming the pad to the shape of the shoe bottom, means for locking the pad in such position, means for inflating the pad to apply pressure to the sole and shoe, and means for automatically unlocking and retracting the sole and shoe gages before inflation of the pad. 40
65. A machine for applying pressure to shoe bottoms having, in combination, a pad for receiving a sole and shoe, means for engaging the heel portion of a sole placed on the pad, and means for finding the heel portion of a shoe mounted on the sole and for simultaneously actuating the sole engaging means to position the heel portion of the sole properly with respect to the shoe bottom. 45
66. A machine for applying pressure to shoe bottoms having, in combination, a pad for receiving a sole and shoe, means for engaging the heel portion of the sole placed on the pad, and means for finding the heel portion of a shoe mounted on the sole and for simultaneously actuating the sole engaging means to position the heel portion of the sole properly with respect to the shoe bottom. 50
- 75

portion of a sole placed on the pad and holding it against movement thereon, and means for finding the heel portion of a shoe mounted on the sole, said means being constructed and arranged 5 by its movement into engagement with the shoe to shift the sole engaging means laterally of the pad to position the heel portion of the sole relatively to the shoe.

67. A machine for applying pressure to shoe bottoms having, in combination, a pad for receiving a sole and shoe, means for engaging the rear portion of a sole on its longitudinal median line and holding it against movement laterally of the pad, means movable into position over the pad 10 for engaging the heel portion of a shoe mounted on the so'e, and connections between the sole engaging means and the shoe engaging means for moving the sole engaging means laterally of the pad during operative movement of the shoe en- 15 gaging means over the pad and thereby shifting the rear portion of the sole into proper trans-verse alinement with the rear portion of the shoe.

68. A machine for applying pressure to shoe bottoms having, in combination, a pad for receiving a sole and shoe, a tongue for engaging the heel portion of a sole on the pad and holding it against movement laterally thereof, means for mounting a shoe on said sole, means for shifting the tongue laterally of the shoe to move 20 the heel portion of the sole into proper alinement with the shoe bottom, and means for returning the tongue to its original position after the sole and shoe have been operated upon.

69. A machine for applying pressure to shoe bottoms having, in combination, a pad for receiving a sole and shoe, a tongue for engaging the heel portion of a sole on its longitudinal median line and holding it against movement laterally of the pad, a gage for finding the heel portion 25 of a shoe mounted on the sole, connections be-tween the shoe gage and the tongue for shifting the latter laterally of the pad to move the sole into proper alinement with the shoe bottom, and means for returning the tongue to its original po- 30 sition after the sole and shoe have been operated upon.

70. A machine for applying pressure to shoe bottoms having, in combination, a pad for receiving a sole and shoe, on the pad, means for 35 engaging the rear portion of a sole on the pad and holding it initially in a predetermined lateral position, a gage for finding the heel portion of a shoe mounted on the sole, mechanism for supporting said shoe gage for movement into and 40 out of operative position over the pad, and means carried by said mechanism for shifting the sole engaging means laterally of the pad to locate the rear portion of the sole relatively to the shoe bottom as the shoe gage moves into operative 45 position.

71. A machine for applying pressure to shoe bottoms having, in combination, a pad for receiving a sole and shoe, a tongue for engaging the rear portion of a sole on its longitudinal me-dian line and holding it against movement lat- 50 erally of the pad, a gage for finding the heel portion of a shoe the forepart of which is clamped against the sole, mechanism for sup- 55 porting said shoe gage for movement relatively to the tongue, and means carried by said sup- 60 porting mechanism for normally maintaining the tongue in a predetermined lateral position but 65 operating upon movement of the shoe gage into 70 operative position to shift the tongue out of said 75

lateral position into a position determined by the work-engaging position of the shoe gage.

72. A machine for applying pressure to shoe bottoms having, in combination, a pad for re-cieving a sole and shoe, a tongue for engaging the rear portion of a sole placed on the pad by an operator and for holding said portion in a predetermined lateral position thereon, said tongue being movable longitudinally of the pad to position the sole lengthwise thereon, a gage 10 for finding the heel portion of a shoe having its forepart clamped against the sole, mechanism for supporting said gage, and connections be-tween said supporting mechanism and the tongue for shifting the tongue laterally of the pad while 15 the shoe gage is finding the shoe and thereby centralizing the sole with respect to the shoe bottom irrespective of the longitudinal position of the tongue.

73. A machine for applying pressure to shoe bottoms having, in combination, a pad for re-cieving a sole and shoe, means for engaging the heel portion of a sole placed on the pad and holding the sole approximately in a central posi-tion thereon, a gage for finding the heel portion 20 of a shoe mounted on the sole, mechanism for supporting the shoe gage for movement heightwise and longitudinally of the pad and for pivotal movement laterally thereof, and means actuated by movement of the shoe gage 25 into operative position for shifting the sole en-gaging means laterally of the pad to bring the sole into proper alinement with the shoe bottom.

74. A machine for applying pressure to shoe bottoms having, in combination, a substantially 30 flat pad for receiving a sole and shoe, means for engaging the heel portion of a sole placed on the pad and holding the sole approximately in a central position laterally of the pad, a gage for 35 finding the heel portion of a shoe mounted on the sole, said gage being movable laterally of the pad about an axis perpendicular to the plane of the pad, and means supporting said gage con-structed and arranged to shift the sole engaging 40 means laterally of the pad to bring the heel portion of the sole into a position determined by 45 the position of the shoe gage when it is engag-ing the shoe.

75. A machine for applying pressure to shoe bottoms having, in combination, a pad for re-cieving a sole and shoe, means for engaging the heel portion of a sole placed on the pad and holding it against movement laterally thereof, a gage for finding and embracing the heel portion of a shoe mounted on the sole, said gage 50 being movable laterally of the pad about an axis substantially perpendicular to the ball line of the shoe on the pad, thereby maintaining the gage in position to embrace the heel portion of the shoe irrespective of its position laterally of the pad, and means carried by the shoe gage for shifting the sole engaging means laterally of the 55 pad to move the rear portion of the sole into proper alinement with the shank and heel por-tions of the shoe bottom.

76. A machine for applying pressure to shoe bottoms having, in combination, a pad for receiving a sole and shoe, a tongue for engaging the heel portion of the sole and initially holding it against movement laterally of the pad, a gage 60 for finding the heel portion of a shoe mounted on the sole, means for shifting the tongue lat-erally of the pad to move the rear portion of the sole into proper alinement with the heel portion of the shoe bottom the position of which 65

has been found by the shoe gage, means for returning the shoe gage automatically to its original position after the sole and shoe have been operated upon, and connections between the 5 shoe gage and the tongue for returning the tongue to its initial position.

77. A machine for applying pressure to shoe bottoms having, in combination, a pad for receiving a sole and shoe, a tongue for engaging 10 the heel portion of a sole on its longitudinal median line and holding it initially in a predetermined position widthwise of the pad, a gage for finding the heel portion of a shoe the forepart of which is clamped against the shoe, mechanism 15 movable heightwise and longitudinally of the pad for supporting said gage, said mechanism being also movable widthwise of the pad about an axis substantially perpendicular to the intersection of the longitudinal median lines of 20 the forepart and rear part of the sole, and means carried by said supporting mechanism for shifting the tongue laterally of the pad to bring the sole into proper alignment with the shoe bottom, said means operating also to return the tongue 25 to its initial position after the sole and shoe have been operated upon.

78. A machine for applying pressure to shoe bottoms having, in combination, a pad for receiving a sole and shoe, a support for said pad, a 30 tongue for holding a sole in an approximately central position widthwise of the pad, a pin on said tongue for engaging a hole in the heel portion of the sole, a shoe gage for finding the heel portion of a shoe the forepart of which is clamped against the sole, mechanism for supporting said shoe gage, said mechanism being arranged for pivotal movement heightwise and lengthwise of the shoe and being also arranged for pivotal movement widthwise of the shoe 40 about an axis perpendicular to the ball line of the shoe, a guide carried by said supporting mechanism and having a sliding bearing on the tongue for shifting the tongue laterally of the pad to align the sole with the shoe bottom as the shoe gage finds the shoe, and means on 45 the pad support for engaging said supporting mechanism and preventing movement widthwise thereof when said mechanism is in its idle position, thereby normally holding the tongue in said central position.

79. A machine for applying pressure to shoe bottoms having, in combination, a pad for receiving a sole and shoe, a tongue having a pin thereon for engaging a hole in the heel portion 55 of a sole placed on the pad and holding said portion against movement transversely of the pad, a gage for finding the heel portion of a shoe the forepart of which is clamped against the sole, mechanism for supporting the gage, 60 said mechanism comprising a plurality of members pivoted for movement heightwise and longitudinally of the pad and arranged also for movement laterally thereof, means for preventing lateral movement of said members when the gage 65 is in an idle position but permitting such movement after the gage is moved out of said position, and a guide carried by said supporting mechanism and engaging the tongue, said guide operating to move the tongue widthwise of the 70 pad as the gage finds the shoe, thereby centralizing the heel portion of the sole relatively to the shoe bottom.

80. A machine for applying pressure to shoe bottoms having, in combination, a pad for receiving a sole and shoe, means for engaging the 75

rear portion of a sole placed on the pad and holding it against movement laterally thereof, means for clamping the forepart of a shoe against the sole, the shank and heel portions of the shoe being thereby spaced from the sole, and means for finding the heel portion of the shoe and simultaneously shifting the sole engaging means laterally of the pad to bring the rear portion of the sole into proper alignment with the shoe bottom while the shank and heel portions of the shoe are spaced from the sole. 5

81. A machine for applying pressure to shoe bottoms having, in combination, a relatively flat pad for receiving a sole and shoe, a tongue for engaging the heel portion of a sole on its longitudinal median line and holding it against movement laterally of the pad, a holdown for clamping the forepart of a shoe against the sole thereby causing the shank and heel portions of the shoe to be spaced from the sole, a gage for finding the heel portion of the shoe, and connections between the gage and the tongue for shifting the latter laterally of the pad upon movement of the gage into shoe engaging position, thereby moving the shank and heel portions of 25 the sole into proper alignment with the shoe bottom while said portions are free from engagement with the shoe. 20

82. A machine for applying pressure to shoe bottoms having, in combination, a pad for receiving a sole and shoe, means for engaging the heel portion of a sole placed on the pad and holding it against movement laterally thereof, 30 gage members for finding the edge face of the sole, means operated by engagement of the gages with the sole for locking them in sole engaging position, shoe gages carried by the sole gages, holdown means for clamping the forepart of a shoe against the sole in the position determined by the shoe gages, the shank and heel portions of the shoe being thereby spaced from the corresponding portions of the sole, and means for finding the heel portion of the shoe 35 and for simultaneously shifting the sole engaging means laterally of the pad to move the shank and heel portions of the sole into proper alignment with the corresponding portions of the shoe bottom, thereby positioning the shank and heel portions of the sole relatively to the shoe while said portions are free from pressure. 40

83. A machine for applying pressure to shoe bottoms having, in combination, a pad for receiving a sole and shoe, a tongue for engaging the heel portion of a sole and holding it in a predetermined position transversely of the pad, 55 a plurality of gages for finding the forepart of the sole, shoe gages carried by the sole gages, means individual to each set of sole and shoe gages for locking that set against movement upon engagement with the sole, means for clamping the forepart of a shoe against the sole in the position determined by the shoe gages, the shank and heel portions of the shoe being thereby held away from the sole and pad, a gage for finding the heel portion of the shoe, said gage being 60 movable in all directions, connections between said shoe gage and said tongue whereby the latter is shifted laterally of the pad to move the rear portion of the sole into proper alignment with the shoe bottom as the shoe gage is moved into engagement with the shoe and while the rear portion of the sole is free from pressure, and means for effecting relative movement between the pad and shoe to bring the rear portions of the pad into pressure applying relation 65 70 75

- to the shank and heel portions of the shoe bottom irrespective of its shape, thereby conforming the pad and the sole to the shape of the shoe bottom.
- 5 84. A machine for applying pressure to shoe bottoms having, in combination, a pad having a surface for receiving a shoe, means for engaging the shoe and pressing it against the surface of the pad, and means movable only in the plane of 10 said surface by movement of the pressing means into shoe engaging position for covering a portion of said surface located outside the periphery of the shoe bottom.
- 15 85. A machine for applying pressure to shoe bottoms having, in combination, a pad for receiving a shoe, means movable heightwise of the shoe for engaging the shoe and pressing it against the pad, means movable toward and from the shoe longitudinally thereof for covering a portion 20 of the pad lying outside the periphery of the shoe bottom, and means for moving the pad covering means longitudinally into operative position relatively to the shoe by heightwise movement of the shoe pressing means into engagement with the shoe.
- 25 86. A machine for applying pressure to shoe bottoms having, in combination, a flexible pad for receiving a shoe, a swinging holdown member for clamping the shoe against the pad, means 30 overlying the pad and movable relatively thereto for masking a portion of its surface lying outside the shoe bottom, and connections between said holdown member and said masking means for moving the latter into operative position longitudinally of the pad during the swinging movement of the holdown member.
- 35 87. A machine for applying pressure to shoe bottoms having, in combination, a pad having a surface for receiving a sole and shoe, a mask plate 40 movable in its own plane toward and from the shoe in a straight path extending longitudinally of the pad, and means for causing the mask plate to expose the same amount of the pad surface between the mask plate and the edge of the shoe bottom irrespective of the size of the shoe.
- 45 88. A machine for applying pressure to shoe bottoms having, in combination, a pad for receiving a sole and shoe, a mask plate overlying the pad for covering portions thereof lying outside the shoe bottom, and means for automatically moving said mask plate longitudinally of the pad into a predetermined position located the same distance from each shoe operated upon irrespective of its size.
- 55 89. A machine for applying pressure to shoe bottoms having, in combination, a pad having a surface for receiving a sole and shoe, a mask plate overlying the forepart of the pad and movable in a straight path longitudinally of the pad to expose more or less of the surface of said forepart during the pressing operation, and means for moving the mask plate into a predetermined longitudinal position relatively to the shoe irrespective of its size before pressure is applied thereto, 60 and for automatically withdrawing the mask plate longitudinally of the pad after pressure has been applied.
- 70 90. A machine for applying pressure to shoe bottoms having, in combination, a pad for receiving a sole and shoe, a holdown lever for clamping the forepart of the shoe against the pad, a mask plate for covering a portion of the pad lying outside the periphery of the shoe, means operated by movement of the holdown lever into engagement with the shoe for moving the mask plate 75 longitudinally of the pad toward and away from the shoe, and means for insuring that the mask plate will be located by said longitudinal movement at the same distance from each shoe operated upon irrespective of the size of the shoe.
- 80 91. A machine for applying pressure to shoe bottoms having, in combination, a pad for receiving a shoe and sole, a holdown lever for pressing the foreparts of the shoe and sole against the pad, a mask plate movable in a predetermined plane 10 relatively to the pad for covering a portion of the pad between the edge thereof and the shoe bottom, and toggle mechanism between the holdown lever and the mask plate for moving the latter a predetermined distance from the shoe 15 irrespective of the size of the shoe.
- 90 92. A machine for applying pressure to shoe bottoms having, in combination, a pad for receiving a shoe, means overlying the forepart of the pad and movable in a straight path longitudinally 20 thereof for masking portions of the pad lying outside the periphery of the shoe bottom, and mechanism carried by said masking means for automatically determining the position thereof longitudinally of the pad in accordance with the size 25 of the shoe.
- 95 93. A machine for applying pressure to shoe bottoms having, in combination, a pad for receiving a sole and shoe, a mask plate overlying the forepart of the pad and movable longitudinally thereof for exposing only a portion of the pad between the mask plate and the shoe bottom, treadle operated means for moving said mask plate toward the shoe, and means controlled by the size of the shoe for stopping said movement at a predetermined point during the operation of said treadle operated means.
- 100 94. A machine for applying pressure to shoe bottoms having, in combination, a pad for receiving a sole and shoe, a mask plate overlying the forepart of the pad and movable relatively thereto for exposing only a portion of the pad between the mask plate and the shoe bottom, means for moving said mask plate toward the shoe, and means actuated by engagement with the toe end 45 of the sole for stopping the mask plate the same distance from each shoe operated upon irrespective of the size of the shoe.
- 105 95. A machine for applying pressure to shoe bottoms having, in combination, a pad for receiving a sole and shoe, a holdown lever for engaging the forepart of the shoe and pressing the shoe and sole against the pad, a mask plate movable longitudinally of the pad for covering a portion thereof between the edge of the pad and 50 the bottom of the shoe, mechanism connected to the holdown lever and to the mask plate for moving the latter toward and away from the shoe when said lever moves into and out of operative position, and means carried by the mask plate for controlling the distance that the mask plate moves in accordance with the size of the shoe irrespective of the distance that the holdown lever moves to engage the shoe.
- 110 96. A machine for applying pressure to shoe bottoms having, in combination, a pad for receiving a sole and shoe, a holdown lever for clamping the forepart of the shoe against the pad, a mask plate movable in a straight path for covering a portion of the pad lying outside the periphery of the shoe, mechanism between the holdown lever and the mask plate for moving the latter toward the shoe during the shoe clamping movement of said lever, and finger means controlled by the size of the shoe for stopping said 75

mask plate at a predetermined distance from the shoe.

97. A machine for applying pressure to shoe bottoms having, in combination, a pad for receiving a sole and shoe, a holdown lever for pressing the forepart of the shoe against the pad, a mask plate for covering a portion of the pad between the edge of the pad and the shoe bottom, a toggle between the holdown lever and the mask plate for moving the mask plate toward or away from the shoe with corresponding movement of the holdown lever, and means mounted on said toggle for breaking the toggle as the holdown lever moves into shoe engaging position, thereby stopping movement of the mask plate toward the shoe before the holdown lever engages the shoe, said means being constructed and arranged to break the toggle when the mask plate is located a predetermined distance from the periphery of the shoe bottom irrespective of the size of the shoe.

98. A machine for applying pressure to shoe bottoms having, in combination, a pad for receiving a sole and shoe, a holdown for pressing the forepart of the shoe against the pad, a mask plate movable longitudinally of the pad for covering a portion of the pad lying outside the periphery of the shoe bottom, a toggle connecting the mask plate to the holdown, means for operating the holdown thereby moving the mask plate toward the shoe, and a finger carried by said toggle and arranged to rest by its own weight on the pad, said finger operating upon movement of the mask plate toward the shoe to engage the sole before the holdown engages the shoe and to break the toggle, thereby stopping movement of the mask plate in a predetermined position relatively to the periphery of the shoe bottom irrespective of the size of the shoe.

99. A machine for applying pressure to shoe bottoms having, in combination, an inflatable pad for receiving a sole and shoe, a holdown for pressing the forepart of the shoe against the pad, a mask plate for covering a portion of the pad outside the periphery of the shoe bottom thereby preventing excessive bulging of the pad around the shoe bottom during the pressure applying operation, a toggle connecting the mask plate to the holdown, said toggle normally being in a straight position, means for moving the holdown into engagement with the shoe, thereby moving the mask plate toward the shoe, a finger on said toggle for engaging the toe end of the sole on the pad and breaking the toggle during movement of the mask plate toward the shoe thereby stopping said movement, said finger being arranged to stop the mask plate the same distance from each shoe operated upon irrespective of its size, and means actuated by the breaking of the toggle for automatically withdrawing the finger from the sole, thereby preventing the finger from catching on the sole when the shoe is removed from the pad.

100. A machine for applying pressure to shoe bottoms having, in combination, a pad for receiving a shoe, a mask plate for exposing only a predetermined portion of the pad between the mask plate and the shoe bottom, means for moving the mask plate longitudinally of the pad into operative position relatively to the shoe, said means including a toggle connected to the mask plate, a finger on said toggle for engaging the shoe during operation of the moving means, thereby breaking the toggle and stopping movement of the mask plate a predetermined distance

from the shoe bottom before said moving means ceases operating, and spring means on the toggle for automatically withdrawing said finger from the shoe.

101. A machine for applying pressure to shoe bottoms having, in combination, a pad for receiving a sole and shoe, gages for finding the edge face of a sole placed on the pad by an operator, means for locking the gages after they have found the sole, a mask plate for covering a portion of the pad lying outside the periphery of the shoe bottom, said mask plate being arranged to move longitudinally of the pad into operative position, means for moving said mask plate into said operative position after the sole gages are locked, and means for releasing and withdrawing said gages while the mask plate is still located in operative position.

102. A machine for applying pressure to shoe bottoms having, in combination, a pad for receiving a sole and shoe, a plurality of gages for finding the forepart of a sole placed on the pad, means operated by engagement of the gages with the sole for locking them individually in operative position, a mask plate movable longitudinally of the pad for covering a portion of the forepart thereof lying outside the periphery of the shoe bottom, means for moving the mask plate a predetermined distance from each shoe operated upon irrespective of the size of the shoe, and means for automatically unlocking and retracting the gages from the sole while the mask plate remains in operative position.

103. A machine for applying pressure to shoe bottoms having, in combination, an inflatable pad for receiving a sole and shoe with its opposite walls initially in contact with each other to form a relatively unyielding support, means for holding a sole and shoe in pressure receiving relation to said support, a mask plate for covering a portion of the support lying outside the periphery of the shoe bottom, means for moving the mask plate longitudinally of the pad into a predetermined position relatively to each shoe operated upon, thereby exposing the same portion of said support irrespective of the size of the shoe, and means for inflating the pad to apply pressure to the shoe bottom.

104. A machine for applying pressure to shoe bottoms having, in combination, an inflatable pad for receiving a sole and shoe, said pad being initially deflated with its upper and lower sides in contact with each other and forming a relatively unyielding wall, means for pressing the sole and shoe into pressure receiving relation to said wall, a mask plate for covering a portion of said wall lying outside the periphery of the shoe bottom, means for moving the mask plate into a predetermined position relatively to each shoe operated upon, and means for inflating the pad to a predetermined pressure irrespective of the size of the shoe, thereby applying substantially the same pressure per unit of area to each shoe operated upon and bulging the exposed portions of the pad between the shoe bottom and the mask plate the same amount for each shoe.

105. A machine for applying pressure to shoe bottoms having, in combination, an inflatable pad for receiving a sole and shoe, said pad being initially deflated with its upper and lower walls in contact with each other to form a relatively unyielding support, means for holding a sole and shoe in pressure receiving relation to said support, thereby locating each sole and shoe operated upon in approximately the same position

heightwise of the pad irrespective of the size of the shoe, a mask plate covering a portion of the pad lying outside the periphery of the shoe bottom, means for insuring that the mask plate will be located at the same distance from each shoe irrespective of its size, and means for inflating the pad to a predetermined pressure, thereby deforming the exposed portion of the pad lying between the mask plate and the shoe bottom the same amount for each shoe operated upon and producing substantially the same roll on each shoe bottom irrespective of the size of the shoe.

106. A machine for applying pressure to shoe bottoms having, in combination, an inflatable pad for receiving a sole and shoe, said pad being normally deflated with its upper and lower walls in contact with each other and forming a relatively unyielding layer, means for pressing each sole and shoe into pressure receiving relation to said layer, thereby locating the sole and shoe in approximately the same position heightwise of the pad irrespective of the size of the shoe, means movable relatively to the pad for covering a portion of the pad lying outside the periphery of the shoe bottom to prevent bulging of said portion when the pad is inflated, means for insuring that the covering means will be located at a predetermined distance from the periphery of the shoe bottom irrespective of its size before pressure is applied to the shoe, and means for inflating the pad to the same pressure for each shoe operated upon, thereby bulging the portions of the pad between the shoe bottom and the covering means the same amount for each shoe and imparting substantially the same roll to each outsole irrespective of the size of the shoe.

107. A machine for applying pressure to shoe bottoms having, in combination, a pad for receiving a sole and shoe, said pad having a shallow chamber which is normally collapsed with its upper and lower walls in contact with each other, thereby forming a relatively solid support for supporting the shoe, means for pressing the sole and shoe into pressure receiving relation to said support, thereby locating the bottom surface of each sole operated upon in approximately the same plane heightwise of the pad irrespective of the size of the sole, a mask plate overlying the pad and having its bottom surface located in a plane fixed relatively to the pad, means for moving the mask plate longitudinally into a predetermined position relatively to each shoe, and means for inflating the chamber in the pad a predetermined amount to apply pressure to the shoe bottom, said inflation causing the exposed portion of the pad between the shoe bottom and the mask plate to bulge the same for each shoe operated upon irrespective of the size of the shoe and thereby producing the same curvature on each outsole.

108. A machine for applying pressure to shoe bottoms having, in combination, an inflatable pad for receiving a sole and shoe, said pad being normally deflated with its upper and lower walls contacting with each other to form a relatively unyielding wall, means for pressing a sole and shoe into pressure receiving relation to said wall and thereby sinking each sole and shoe operated upon approximately the same distance into said wall irrespective of the size of the shoe, means fixed heightwise of the pad for covering a portion thereof lying outside the periphery of the shoe bottom, means for moving said covering means in its own plane a distance controlled by the size of the shoe to locate said means in the same

position relatively to the periphery of each shoe, and means for inflating the pad to a predetermined pressure for each shoe irrespective of its size thereby causing substantially the same pressure per unit of area to be applied to each shoe. 5

109. A machine for applying pressure to shoe bottoms having, in combination, an inflatable pad for applying pressure to a sole and shoe, said pad having upper and lower walls normally engaging each other to form a relatively incompressible support, a relatively flexible pad overlying said inflatable pad, said flexible pad having a slightly compressible forward portion and a more compressible rear portion, means for clamping the foreparts of a sole and shoe against the forward portions of the pads, thereby locating the forepart of the sole of each shoe operated upon in substantially the same plane heightwise of the pads, and means for distorting the inflatable pad a predetermined amount irrespective of the size of the shoe operated upon, thereby applying the same pressure per unit of area to each shoe and producing the same roll on its outsole through the deformation of the portions of the inflatable pad located outside the periphery of the shoe bottom. 15 20 25

110. A machine for applying pressure to shoe bottoms having, in combination, an inflatable pad for applying pressure to a sole and shoe, means for inflating the pad to a predetermined pressure to expand the pad and to apply pressure to a shoe mounted thereon, and means movable relatively to the shoe on the pad for limiting the expansion of the pad to the same amount for each shoe operated upon, thereby applying substantially the same pressure per unit of area to each shoe irrespective of its size and producing the same convexity on its outsole. 30 35

111. A machine for applying pressure to shoe bottoms having, in combination, a thin inflatable pad for applying pressure to a sole and shoe, a relatively thick pad overlying said inflatable pad, means for inflating the inflatable pad to apply pressure to the bottom of a shoe mounted on the thick pad, and means for limiting the deformation of the portions of the pad lying outside the periphery of the shoe bottom in accordance with the size of the shoe being operated upon, thereby producing substantially the same convexity on the outsole of the shoe irrespective of its size. 40 45 50

112. A machine for applying pressure to shoe bottoms having, in combination, an inflatable pad for applying pressure to a sole and shoe, means for inflating the pad to a predetermined pressure to expand the pad and apply pressure to a shoe mounted thereon, a mask plate for covering a portion of the pad lying outside the periphery of the shoe bottom, and finger means controlled by the size of the shoe for locating the mask plate a predetermined distance from the periphery of each shoe operated upon irrespective of its size, thereby causing the portions of the pad between the edges of the shoe and the mask plate to bulge the same for each shoe so that substantially the same pressure per unit of area will be applied to each shoe bottom. 55 60 65

113. A machine for applying pressure to shoe bottoms having, in combination, an inflatable pad for applying pressure to a sole and shoe, said pad being initially deflated with its upper and lower sides in contact with each other, a hold-down for pressing the forepart of a shoe into pressure receiving relation to said pad, the shank and heel portions of the shoe being thereby spaced from the rear portion of the pad, a mask plate 70 75

movable in a straight path longitudinally of the pad for covering a portion thereof lying outside the periphery of the shoe bottom, a finger controlled by the size of the shoe for locating the mask plate the same distance from each shoe operated upon irrespective of its size, means for moving the rear portion of the pad into engagement with the shank and heel portions of the shoe bottom without applying substantial pressure thereto, and means for inflating the pad to a predetermined pressure, thereby expanding the pad and applying pressure to the entire shoe bottom, the deformation of the forward portion of the pad being substantially the same for each shoe operated upon irrespective of its size and thereby producing the same convexity on its forepart.

114. A machine for applying pressure to shoe bottoms having, in combination, a pair of operating stations each arranged to receive a sole and shoe, means for mounting a sole and shoe on each station, means for locking the sole and shoe on each station, means for applying pressure to each sole and shoe, levers for actuating said pressure applying means from either station, and means operated by the return of the lever at either station toward its initial position after actuating the pressure applying means for automatically releasing the means which locks the sole and shoe on the opposite station.

115. A machine for applying pressure to shoe bottoms having, in combination, a pair of operating stations each arranged to receive a sole and shoe, means for mounting a sole and shoe on each station, means for locking the sole and shoe on each station, means for applying pressure to each sole and shoe, levers for actuating said pressure applying means from either station, and means operated automatically by the lever at one station after it has actuated the pressure applying means for releasing the locking means on the other station.

116. A machine for applying pressure to shoe bottoms having, in combination, a pair of operating stations, a pad in each station arranged to receive a sole and shoe, a holddown on each station for clamping a sole and shoe against the pad, means for locking each holddown in shoe clamping position, means separate from said holddown for supporting the heel portion of each shoe against pressure from the pad, separate means for locking each heel supporting means, mechanism on each station for effecting relative movement of the pad and shoe to apply pressure to the shoe bottom, and means on either station operated by the actuation of the pressure applying mechanism on the opposite station for automatically releasing the means for locking the holddown and the heel supporting means on the first-named station in the order named.

117. A machine for applying pressure to shoe bottoms having, in combination, a pair of operating stations each provided with an inflatable pad, means for clamping the forepart of a shoe against each pad, separate means for pressing the shank and heel portions of the pad and shoe together, means for locking said pressing means in operative position, means for inflating each pad to apply pressure to the shoe bottom, a lever on each station for actuating said inflating means, and means at either station operated automatically by the actuating lever at that station when said lever is returning to its idle position after actuating the inflating means, for releasing the

means for locking the shank and heel pressing means on the opposite station.

118. A machine for applying pressure to shoe bottoms having, in combination, a pair of operating stations each provided with an inflatable pad, a holddown on each station for clamping the foreparts of a sole and shoe against the pad, means for locking each holddown in operative position, means for supporting the heel portion of each shoe against pressure from its pad, means for locking each heel supporting means in operative position, means common to both stations for inflating the pads separately to apply pressure to the soles and shoes thereon, a treadle operated lever on each station for actuating said inflating means, and mechanism operated by the actuation of the treadle operated lever on either station for automatically releasing the forepart holddown and heel supporting means on the opposite station after said lever has first actuated the inflating means on the first-named station.

119. A machine for applying pressure to shoe bottoms having, in combination, a pair of operating stations each provided with a substantially flat inflatable pad, means on each station for clamping the foreparts of a sole and shoe on the pad, thereby holding the shank and heel portions of the shoe away from the pad, means at each station operable to move the rear portion of the pad against the shank and heel portions of the shoe bottom thereby conforming the pad to said shoe bottom, means for locking the pad moving means in operated position, means for inflating each pad to apply pressure to the sole and shoe, a lever at each station for actuating the pad inflating means, and means actuated by return of the lever at either station to idle position after actuating the inflating means for automatically unlocking the pad moving means on the opposite station.

120. A machine for applying pressure to shoe bottoms having, in combination, a pair of operating stations each provided with an outwardly facing inflatable pad for receiving a sole and shoe, said pads being normally located in a substantially flat position, holddowns for clamping the foreparts of a sole and shoe against the pad in each station, thereby causing the shank and heel portions of the shoe to be spaced from the pad, mechanism for supporting the heel portion of each shoe against pressure from its pad, separate means for locking each holddown and each heel supporting mechanism in operative positions, means on each station for moving the rear portion of each pad into pressure applying relation to the shank and heel portions of the shoe bottom, thereby conforming the sole and the pad to the shape of the shoe bottom irrespective of the size of the shoe, means for locking each pad in conformed position, means for inflating each pad separately to apply pressure to the shoe thereon, means for automatically limiting the pressure to a predetermined amount, and means actuated by operation of the pad inflating means in either station for automatically relieving the pressure in the pad on the other station and for thereafter releasing the locked holddown, pad conforming and heel supporting mechanisms associated with said other station to permit removal of the shoe.

121. A machine for applying pressure to shoe bottoms having, in combination, a pad for receiving a sole and shoe, a holddown for clamping the shoe on the pad, means for actuating said holddown, and means for locking said actuating means, said locking means comprising a toggle,

means for straightening the toggle, and means on the toggle for engaging said actuating means only when the toggle is straight.

122. A machine for applying pressure to shoe bottoms having, in combination, a pad for receiving a sole and shoe, a holddown for pressing the shoe against the pad, a cam operable to actuate said holddown, and means for locking said cam in operated position, said means comprising a toggle, a member on the cam for straightening said toggle, and a pawl carried by the toggle for engaging the cam only when the toggle is straight, thereby locking the cam.

123. A machine for applying pressure to shoe bottoms having, in combination, a pad for receiving a sole and shoe, a holddown for pressing the shoe against the pad, means movable about a fixed axis for actuating said holddown, and means for locking said actuating means in operated position, said locking means including a toggle and means thereon which, when the toggle is straight, engages said actuating means and holds it against movement out of said operated position and, when the toggle is broken, lies outside the path of movement of said actuating means.

124. A machine for applying pressure to shoe bottoms having, in combination, a pad for receiving a sole and shoe, a holddown lever for pressing the shoe against the pad, a cam member movable about a fixed axis for operating said holddown lever, said cam member having ratchet teeth on a portion thereof, a toggle having means thereon for engaging said teeth and locking the cam in operated position, said means being constructed and arranged when the toggle is broken to lie outside the path of said cam and, when the toggle is straight, to extend into said path in a position permitting movement of the cam in one direction but preventing its movement in the opposite direction thereby locking the cam, and means carried by the cam for straightening the toggle as the cam moves the holddown lever into engagement with the shoe.

125. A machine for applying pressure to shoe bottoms having, in combination, a pad for receiving a sole and shoe, a holddown lever for pressing the shoe against the pad, a movable cam for bringing the holddown lever against the shoe, treadle operated means for moving said cam, a toggle carrying pawls constructed and arranged when the toggle is straight to lock the cam in operated position and, when the toggle is broken, to release said cam, means carried by the cam for straightening the toggle during the movement of the cam, thereby causing the pawls to lock the cam in operated position, and means independent of the cam for breaking the toggle to release the cam.

126. A machine for applying pressure to shoe bottoms having, in combination, a pad for receiving a sole and shoe, a holddown lever for pressing the shoe against the pad, a cam member movable about a fixed axis for actuating said holddown lever, said member having teeth on a part of its periphery, a toggle having pawls pivoted thereon for engaging the teeth on the cam member and locking said member in operated position, said pawls being urged yieldingly toward the cam member by springs and being so positioned and arranged that when the toggle is broken they will lie outside the path of the cam member but, when the toggle is straight, they will ride yieldingly over the teeth on said member and, at the end of its operative movement, will

engage a tooth to lock the cam member in operated position, means pivoted loosely on the cam member for automatically straightening the toggle as the cam member is moved into operated position, and treadle operated means independent 5 of the cam for breaking the toggle to release the cam.

127. A machine for applying pressure to shoe bottoms having, in combination, a pair of operating stations located side by side, a pad on each station for applying pressure to a sole and shoe, a forepart holddown for each pad for clamping a shoe thereon, a cam for actuating each hold-down, means at each station for operating each cam, separate means for locking each cam in 10 operated position, and means actuated by treadle operated means on each station for releasing the cam locking means in the other station.

128. A machine for applying pressure to shoe bottoms having, in combination, a pair of operating stations located side by side, a pad on each station for applying pressure to a sole and shoe, a forepart holddown lever for each pad for clamping a shoe thereon, a cam for actuating each lever, treadle operated means at each station 20 for operating each cam, separate means for locking each cam in operated position, means carried by each cam for automatically operating its locking means, and means actuated by a treadle on either station for releasing the cam 25 locking means on the opposite station.

129. A machine for applying pressure to shoe bottoms having, in combination, an inflatable shoe receiving pad inclined downwardly in a position to be viewed by an operator, gages operable to position a shoe relatively to a sole on the pad, means for locking the gages in operated 35 position, means for inflating the pad, a treadle for actuating said inflating means, and means actuated by operation of said treadle for automatically unlocking the positioning gages before the pad is inflated.

130. A machine for applying pressure to shoe bottoms having, in combination, a forwardly and downwardly inclined inflatable pad for applying 45 pressure to a sole and shoe, said pad being normally located in a substantially flat position, gages on the pad operable to position a shoe relatively to a sole placed thereon, treadle operated means for locking the gages in operated 50 position, a holddown for clamping the foreparts of the sole and shoe against the pad thereby holding the shank and heel portions of the shoe away from the pad, means for moving the rear portion of the pad into engagement with the 55 shank and heel portions of the shoe thereby conforming the pad to the shape of the shoe bottom, means for inflating each pad, a treadle for operating said inflating means, and separate means cooperating with said treadle for automatically unlocking the positioning gages before 60 inflation of the pad.

131. A machine for applying pressure to shoe bottoms having, in combination, a pad for receiving a shoe, said pad being normally located 65 in a substantially flat position, a holddown member for pressing the forepart of the shoe against the pad thereby holding the shank and heel portions of the shoe away from the pad, a treadle for operating said holddown member, means for moving the rear portion of the pad into engagement with the shank and heel portions of the shoe thereby conforming the pad to the shape 70 of the shoe bottom, mechanism for actuating the pad moving means, and means for causing the 75

holddown treadle to operate said actuating mechanism after it has operated the holddown member.

132. A machine for applying pressure to shoe bottoms having, in combination, a pad for receiving a shoe, said pad being initially located in a substantially flat position, a holddown for clamping the forepart of the shoe against the pad thereby holding the shank and heel portions of the shoe away from the pad, means for actuating said holddown, a treadle separable from the actuating means for operating said means, means for connecting the treadle to said actuating means on its first depression, means for moving the rear portion of the pad against the shank and heel portions of the shoe thereby conforming the pad to the shape of the shoe bottom, a lever for actuating said moving means, means carried by said lever and cooperating with said connecting means for connecting said lever to the holddown treadle, and means on the holddown actuating means for disengaging said connecting means therefrom prior to the connection of the treadle to said actuating lever, thereby causing the treadle to operate said lever on its second depression without operating said actuating means.

133. A machine for applying pressure to shoe bottoms having, in combination, a pair of operating stations, an inflatable pad on each station for receiving a shoe, means on each station for pressing the shoe against the pad, means for supplying fluid under pressure to each pad, means for controlling the admission of fluid to the pads, said means comprising valve mechanism having inlet and outlet ports individual to each pad, means for positioning said valve mechanism simultaneously to admit fluid to one pad and to exhaust fluid from the other pad, and means for automatically stopping the flow of fluid under pressure to the pad when the pressure therein reaches a predetermined amount.

134. A machine for applying pressure to shoe bottoms having, in combination, a pair of operating stations located side by side, an inflatable pad on each station for receiving a shoe, means on each station for pressing the shoe against the pad, means for inflating each pad with fluid under pressure to apply pressure to the shoe, means for controlling the admission of fluid to said pads, said means including valve mechanism constructed and arranged to permit fluid to enter only one pad at a time, and means for locating said valve mechanism in a position to admit fluid to the pad which is to apply pressure to a shoe and for exhausting the other pad prior to the operation of said inflating means and without further operation of said locating means.

135. A machine for applying pressure to shoe bottoms having, in combination, a pair of operating stations located side by side, an inflatable pad on each station for receiving a shoe, means on each station for pressing the shoe and pad together thereby clamping the shoe on the pad, a treadle at each station for operating said pressing means, means for inflating each pad, mechanism for causing said inflating means to inflate each pad separately, and means actuated by the treadle at either station as said treadle operates the pressing means for positioning said mechanism to exhaust the pad at the opposite station and to permit the pad at the station at which the treadle is located to be subsequently inflated.

136. A machine for applying pressure to shoe bottoms having, in combination, a pair of operat-

ing stations located side by side, an inflatable pad on each station for receiving a shoe, means on each station for pressing the shoe and pad together thereby holding the shoe on the pad, a treadle at each station for operating said pressing means, means for inflating each pad, valve mechanism for controlling said inflating means to inflate only one pad at a time, means actuated by depression of the treadle at either station as it operates the pressing means on that station for positioning said valve mechanism for inflating the pad on that station and for permitting the pad on the other station to exhaust, and separate means actuated by further depression of said treadle for actuating the inflating means.

137. A machine for applying pressure to shoe bottoms having, in combination, a pair of operating stations both facing an operator, an inflatable pad on each station for receiving a shoe, a holddown member on each station for pressing the shoe against the pad, a treadle for operating each holddown, means for inflating each pad from a common source of supply, valve mechanism for causing said inflating means to inflate each pad separately, means actuated by depression of the treadle on either station for positioning said valve mechanism for permitting subsequent inflation of the pad at that station and for exhausting the other pad, means operated by a subsequent depression of the same treadle for actuating the inflating means, and means for automatically stopping said inflating means when the pressure in the pad reaches a predetermined amount.

138. A machine for applying pressure to shoe bottoms having, in combination, a pair of operating stations both facing an operator, an inflatable pad on each station for receiving a shoe, a holddown member on each station for pressing the shoe against the pad, a treadle for operating each holddown, means for inflating each pad, valve mechanism for controlling said inflating means to permit inflation of one pad and to exhaust the other pad, means actuated by depression of the treadle on either station for positioning the valve mechanism to permit inflation of the pad on that station and to exhaust the pad on the other station, means actuated by a second operation of the same treadle for actuating the inflating means to inflate the pad at that station, and separate means associated with said inflating means for automatically stopping the inflating means when a predetermined pressure is obtained in the pad.

139. A machine for applying pressure to shoe bottoms having, in combination, a pair of operating stations located side by side, an inflatable pad on each station for receiving a sole and shoe, a holddown for each station for pressing the shoe against the pad, a treadle at each station for operating each holddown, toggle means for locking each holddown in operated position, single means for inflating each pad separately, valve mechanism for controlling the operation of said inflating means, said valve mechanism being constructed and arranged to permit the pad on one station to be inflated and to cause the pad on the other station to exhaust, means actuated by the treadle at either station after it has operated the holddown on that station for positioning said controlling mechanism to inflate the pad on said station, means operated by further movement of the same treadle for actuating the inflating means, and means operated simultaneously by said further movement of said treadle for unlocking the holddown on the other station.

140. A machine for applying pressure to shoe bottoms having, in combination, an inflatable pad for receiving a sole and shoe, means for inflating the pad to apply pressure to the sole and shoe, a valve for controlling the inflation of the pad, means for normally maintaining the valve in a position to prevent inflation of the pad, means for actuating the valve to permit inflation of the pad, and means for automatically returning the valve to its original position to prevent further inflation of the pad after a predetermined pressure has been obtained therein.

141. A machine for applying pressure to shoe bottoms having, in combination, an inflatable pad for receiving a sole and shoe, means for inflating said pad to apply pressure to the sole and shoe, said means comprising a reservoir for holding fluid, a pump and a valve, means for normally maintaining the valve in a position to prevent inflation of the pad, means for actuating the valve to cause inflation of the pad, and fluid actuated means for automatically returning the valve to its initial position after a predetermined pressure has been obtained in the pad.

142. A machine for applying pressure to shoe bottoms having, in combination, an inflatable pad for receiving a sole and shoe, means for inflating the pad to apply pressure to the sole and shoe thereon, said means including a reservoir for holding fluid, a pump, and a valve for opening and closing an outlet port in a pipe line leading to the pad, toggle means for causing said valve normally to leave said outlet port open and to permit fluid to pass therethrough, means for operating said toggle means to cause the valve to close said outlet port and thereby force fluid under pressure into the pad, and means operated by the pressure in the pad for automatically causing said toggle means to return said valve to its original position to open said outlet port.

143. A machine for applying pressure to shoe bottoms having, in combination, an inflatable pad for receiving a sole and shoe, means for inflating the pad to apply pressure to a sole and shoe thereon, said means including a reservoir for holding fluid, a pump, and a slide valve for opening and closing an outlet port in a pipe line leading to the pad, a toggle for causing the valve normally to permit fluid to pass through said outlet port, means for operating said toggle to prevent fluid from passing through said port thereby forcing it into the pad, means for regulating the pressure in the pad, and means actuated by the operation of said regulating means for automatically operating said valve to open said outlet port and stop inflation of the pad after the pressure therein reaches a predetermined amount.

144. A machine for applying pressure to shoe bottoms having, in combination, an inflatable pad for receiving a sole and shoe, means for inflating the pad to apply pressure to the sole and shoe, said means comprising a reservoir for holding fluid, a motor driven pump, and a slide valve for opening and closing a pipe line leading to the pad, a toggle normally holding the valve in a position which leaves the pipe line open, means for straightening the toggle to close the pipe line and force fluid under pressure into the pad, pressure regulating means for controlling the pressure in the pad and expelling excess fluid from the pipe line, and means actuated by the operation of said regulating means for automatically breaking the toggle and opening the pipe line, thereby preventing further fluid from being expelled from the pipe line through the pressure regulating means, said

toggle breaking means comprising a lever pivoted adjacent to the toggle and having means thereon for catching fluid expelled from said regulating means whereby the lever is operated to break the toggle, said lever also having means thereon for returning it to its initial position after the toggle is broken.

145. That improvement in methods of making shoes the soles of which are to be attached by cement which comprises, locating a sole treated with tacky cement relatively to a shoe bottom likewise treated with tacky cement, applying pressure to the entire foreparts of the sole and shoe while holding the shank and heel portions of the sole entirely out of contact with corresponding portions of the shoe bottom so that no parts of said portions can adhere to each other through such contact, moving the shank and heel portions of the sole and shoe into engagement with each other while maintaining the pressure applied to their foreparts, thereby laying the sole on the shoe bottom progressively from forepart to heel, and applying pressure to the entire areas of said shank and heel portions.

146. That improvement in methods of making shoes the soles of which are to be attached by an initially tacky cement which comprises, relatively positioning the foreparts of a cement treated sole and shoe and then bringing said foreparts into engagement with each other, pressing said foreparts together over their entire areas while holding the entire shank and heel portions of the shoe spaced from the sole, thereby preventing even light adhesion between said portions, and while maintaining the pressure on said foreparts moving the rear portions of the sole into engagement with the shoe bottom, thereby conforming the sole to the shank and heel portions of the shoe bottom progressively from ball line to heel.

147. That improvement in methods of making shoes the soles of which are to be attached by an instantaneous cement which comprises, locating the foreparts of a sole and shoe relatively to each other, applying relatively light pressure to the entire area of said foreparts while holding the entire shank and heel portions of the shoe spaced from the corresponding portions of the sole, thereby sticking said foreparts together in proper position but preventing the shank and heel portions from sticking together even lightly at any parts thereof, moving the shank and heel portions of the sole into engagement with the corresponding portions of the shoe bottom irrespective of the shape of the shoe while maintaining the pressure undiminished at said foreparts, thereby conforming the sole progressively to the contour of the shoe bottom and applying relatively light pressure to said shank and heel portions to cause said portions immediately to adhere to each other, and then applying heavier pressure uniformly to the entire shoe bottom to attach the sole permanently to the shoe bottom.

148. That improvement in methods of making shoes the soles of which are to be attached by cement which comprises, positioning the foreparts of a sole and shoe relatively to each other with the sole located in a substantially flat position, pressing said foreparts against each other thereby holding said foreparts against displacement but with the shank and heel portions of the shoe spaced from corresponding portions of the sole, and shifting only the portion of the sole rearwardly of the ball line laterally of the shoe bottom into proper transverse alignment with the shank and

heel portions of the shoe while said rear portion is free from engagement with the shoe bottom.

149. That improvement in methods of making shoes the soles of which are to be attached by relatively tacky cement which comprises relatively positioning the foreparts of a sole and shoe the attaching surfaces of which have been treated with tacky cement, pressing the foreparts of the shoe and sole together from the toe end to the ball line while holding the shank and heel portions of the shoe out of contact with the sole, shifting the portion of the sole rearwardly of the ball line into proper transverse alignment with the shank and heel portions of the shoe bottom

15 while said portion is still free from engagement with the shoe bottom and while the foreparts of the sole and shoe are still pressed together, and moving the portion of the sole rearwardly of said ball line heightwise of the shoe against the shank and heel portions of the shoe bottom while holding said portion of the sole in its shifted position, thereby sticking the sole to the shoe bottom progressively from forepart to heel irrespective of the shape of the shoe bottom while insuring that

20 the portion of the sole rearwardly of the ball line will initially engage the shoe bottom in the proper transverse position.

150. That improvement in methods of making shoes the soles of which are to be attached by cement which comprises relatively positioning the foreparts of a sole and shoe the attaching surfaces of which have been treated with cement, 5 pressing the foreparts of the shoe and sole together while holding the shank and heel portions of the shoe out of contact with the sole, shifting the rear portion of the sole into proper transverse alignment with the shank and heel portions of the shoe bottom while said rear portion is still free from engagement with the shoe bottom, moving the rear portion of the sole heightwise of the shoe against the shank and heel portions of the shoe bottom while maintaining the full pressure 10 on the foreparts of the sole and shoe and while holding said rear portion in its shifted position, thereby applying the sole to the shoe bottom progressively from forepart to heel irrespective of the shape of the shoe bottom while insuring 15 that the sole will initially engage the shoe bottom in the proper transverse position, and applying pressure to conform the sole to the shoe bottom and to cause the sole to become attached thereto.

SIDNEY J. FINN.

CERTIFICATE OF CORRECTION.

Patent No. 2,124,654.

July 26, 1938.

SIDNEY J. FINN.

It is hereby certified that error appears in the printed specification of the above numbered patent requiring correction as follows: Page 8, first column, line 20, for the word "button" read bottom; page 26, second column, line 29, claim 54, for "portions" read portion; and that the said Letters Patent should be read with this correction therein that the same may conform to the record of the case in the Patent Office.

Signed and sealed this 7th day of February, A.D. 1939.

Henry Van Arsdale.
